UNITED STATES PATENT OFFICE.

PERCY BERESFORD WRIGHT KERSHAW, OF LONDON, ENGLAND, ASSIGNOR
TO HENRY DUNDAS, OF SAME PLACE.

TYPE-WRITING, TYPE-SETTING, OR ANALOGOUS MACHINE AND TELEGRAPHIC APPARATUS.

SPECIFICATION forming part of Letters Patent No. 677,311, dated June 25, 1901.

Application filed September 15, 1900. Serial No. 30,188. (No model.)

To all whom it may concern:

Be it known that I, PERCY BERESFORD WRIGHT KERSHAW, a subject of the Queen of England, residing at London, England, 5 have invented certain new and useful Improvements in or Relating to Type-Writing, Type-Setting, or Analogous Machines and Telegraphic Apparatus, (for which I have made application for Letters Patent in Great 10 Britain, No. 3,390, dated February 21, 1900,) of which the following is a specification.

The object of this invention is to increase the speed of operation of those classes of machines which are employed to obtain a permanent record of mental ideas in characters representing words, such as type-writers, type-composers, telegraphic apparatus, machines for preparing type, machine record-strips, and the like.

20 The invention comprises the employment of a permutation of mechanical marks to represent each letter or other character or groups of letters or characters—that is to say, each character or group of characters is represented by a given order or sequence of mechanical pieces or marks—the permutations being operated by mechanism, so that by actuating a key or its equivalent a record is obtained of two or more characters in a desired 25 sequence, while by actuating the same key along with a second key as a chord a record is obtained of a different sequence of characters—that is to say, the key or keys actuated by the operator or their equivalent does 30 not represent merely a particular character or group of characters, but arranges a permutation of mechanical marks which selects and assembles the individual dies or matrices in the order requisite to make the de- 35 sired record. For example, by depressing a key two characters—say “at”—are recorded. By depressing the same key, together with another key, (which I call a “shift-key,”) as one strikes a chord on a piano, a different 40 record is obtained—say “a d.” By striking the same key and a different shift-key a third sequence of characters is recorded—say “a q”—a fresh sequence being recorded according to the shift-key used. Each shift-key is 45 common to a series of keys forming thereby other sequences. Moreover, chords may be

struck consisting of two or more normal keys or of normal and shift keys. These groups of characters are not represented in the recording apparatus by what are called 55 “logotypes.” No corresponding stamp or die representing a group need be used; but the single characters represented in the group are selected and arranged in the desired sequences, whether these be raised stamps, as 60 used in type-writers, printer’s type, as in composing-machines, or matrices, as in linotype or other type forming and setting machines.

The invention can be applied either to select and arrange such stamps or matrices at once or to operate the existing keyboards of machines now in use.

Broadly, the apparatus employed for carrying out the invention comprises three main 70 parts: first, a keyboard or equivalent, by which the operator indicates the characters he desires to select; second, a recording mechanism, which establishes a simultaneous mechanical record in an arbitrary fixed order 75 of all the characters indicated by one operation of the keyboard, and, third, a selecting mechanism, which actuates this record, selecting one character at a time in the order indicated by the operator. The mechanical 80 record when actuated by the selecting mechanism may operate any convenient form of mechanism to operate the stamps of a type-writer, select the type of a composing-machine, arrange matrices on a mold for a composing and casting machine, or control the 85 contacts of a telegraphic transmitter.

I will now describe by way of example a convenient construction of apparatus for carrying out the invention as applied to the 90 working of a linotype composing and casting machine, reference being made to the accompanying drawings, of which—

Figure 1 is a right-hand side elevation of the complete apparatus, showing the frame 95 of the linotype-machine it is to operate. Fig. 2 is a left-hand side elevation of the recording and selecting mechanisms, the left-hand standard being removed. Fig. 3 is a front view of these mechanisms, part broken away. 100 Fig. 4 is a plan of the same. Fig. 5 is a plan of the keyboard, part in section, on the line

V V of Fig. 7. Fig. 6 is a diagrammatic representation of an alternative arrangement of keys to that shown in Fig. 5. Fig. 7 is a longitudinal vertical section on line VII VII of Figs. 5 and 9. Fig. 8 is a side elevation of the keyboard, showing the automatic vowel-control mechanism. Fig. 9 is a sectional plan on the line IX IX of Fig. 7. Fig. 10 is a transverse section on line X X of Fig. 5. Fig. 11 is a sectional plan of portion of keyboard, showing the automatic vowel-control mechanism of the lower section of board. Fig. 12 is a vertical section on line XII XII of Fig. 11. Figs. 13 and 14 are detail views, on an enlarged scale, illustrating parts of the automatic vowel-reversal mechanisms. Fig. 15 is a sectional plan on line XV XV of Fig. 14. Fig. 16 is a cross-section on line XVI XVI of Fig. 13. Fig. 17 is an elevation, part broken away and part in section, of the record-drum and its shield. Fig. 18 is a cross-section on the line XVIII XVIII of Fig. 17. Fig. 18^a is a perspective view of one of the record-drum studs. Figs. 19 and 20 are a side and end elevation, respectively, showing the mechanisms connected with the positioning of the record-studs. Fig. 20^a is a detail of part of this mechanism. Figs. 21, 21^a, and 21^b are detail views showing the mechanism for giving movement to the record-drum, in three positions. Figs. 22 and 23 are a side and front view, respectively, of the mechanisms controlling the position of the record-stud latches. Figs. 23^a to 23^c show details of part of these mechanisms. Fig. 24 is a section on the line x x of Fig. 2, the permutation-bars and some other parts being omitted for the sake of clearness. Fig. 25 is a section on the line y y of Fig. 2, parts being omitted for the sake of clearness. Fig. 26 is a front elevation showing the permutation-bars for the upper section of the keyboard and some of their operative mechanisms. Fig. 26^a is a section on the line XXVI^a XXVI^a of Figs. 24, 25, and 26, showing only those parts comprising the permutation-bar cut-out release mechanism. Fig. 26^b is a section on the line XXVI^b XXVI^b of Figs. 24, 25, and 26, showing only those parts comprising the distance-pieces-shifting mechanism. Figs. 27 and 27^a are sections on the line XXVII XXVII of Figs. 24, 25, and 26, showing the automatic vowel-control permutation-bar mechanism in two positions. Figs. 27^b and 27^c are elevations of these permutation-bars detached. Fig. 28 is a section on line XXVIII XXVIII of Figs. 24, 25, and 26, showing the permutation-bar mechanisms of syllabic keys in inoperative position. Figs. 29 and 30 are similar views showing these parts in operative positions. Fig. 31 is a side elevation showing the reversal permutation-bar in inoperative position. Fig. 32 is a front elevation of the permutation-bars and associated mechanism used in effecting the reversal of sections of the keyboard. Fig. 33 is a section on the line XXXIII XXXIII of Fig. 32, showing these mechanisms in inoperative

position. Fig. 34 is a similar view in operative position. Fig. 35 is a side view of a single-character permutation-bar, showing its three positions. Fig. 36 is a side view of the disk-valve and its operative bars. Fig. 37 is a plan of the same. Figs. 37^a and 37^b are perspective views of parts of the valve-operating mechanism. Fig. 37^c is a detail of the mechanism directly operating on a lino-key. Fig. 38 is a diagrammatic view showing the arrangement of the valve-ports. Fig. 39 is a diagrammatic view showing the arrangement of the selecting-studs on the assembling-drum. Fig. 40 is a diagram showing the arrangement of the permutation-bars, the selecting-stud arms, and the assembling-drum selecting-studs. Fig. 41 is a diagram of an alternative arrangement of keyboard, and Fig. 42 is a diagram showing the arrangement of selecting-studs for the same. Fig. 43 is a side view, and Fig. 44 is a plan, of a record-strip-punching mechanism. Fig. 45 is a diagrammatic view showing the air connections between the keyboard wind-box and the bellows recording the record-studs.

Like characters indicate like parts in all the figures.

For the purposes of this description the keyboard is considered the front of the machine, and the terms "left hand" and "right hand" of the apparatus refer to the left and right hand of the operator when facing the keyboard.

1 is the frame of a linotype-machine of any usual construction, and 2 the keys of the keyboard operating the same.

The apparatus forming the subject of this invention may be arranged in any convenient position in relation to the linotype-machine to suit the exigencies of space. As shown, the keyboard 3 is placed adjacent to the keyboard of the linotype-machine and supported on brackets 4, bolted onto the framework of the said machine, the operator being thus enabled to readily operate the justifying and casting levers of the same. The rest of the apparatus, comprising the recording and selecting mechanisms, is placed behind the linotype-machine and is carried on a base-plate 5, on which are bolted two standards 6 and 7, connected at the top by cross-plates 8 and 9.

In the example now described the mechanisms are operated pneumatically, the air-ducts connecting the keyboard mechanism with the recording mechanism being carried in a common box 10 and those connecting the selecting mechanism with the linotype-keys in the box 11.

To enable the description of the various mechanisms to be more easily followed before describing the apparatus in detail, a short summary may conveniently be given of the arrangement of the principal parts and their functions.

As stated above, the apparatus may be divided into three parts—a keyboard, a recording mechanism, and a selecting mechanism.

The keyboard 3 comprises a number of keys or their equivalent, the depression of any one of which admits air into one or more of a number of air-ducts leading to the recording mechanism.

The recording mechanism comprises an intermittently-revolving drum, hereinafter called the "record-drum," provided with a number of adjustable studs called "record-studs," which are placed in and out of operative position by arms actuated by the air-ducts coming from the keyboard. Corresponding to each of these record-studs is a vertical bar, hereinafter called a "permutation-bar," capable of both a swinging and an up-and-down movement. Normally these bars are held at a slight angle; but when a record-stud is placed in operative position its corresponding permutation-bar is swung back and placed over the free end of a short pivoted arm. The free ends of these arms, hereinafter called "selecting-stud" arms, rest on the circumference of a constantly-revolving drum, hereinafter called the "assembling drum," which constitutes the selecting mechanism. Arranged spirally or in a zigzag fashion around the circumference of this drum is fixed a number of studs, hereinafter called "selecting-studs," one or more of these studs lying in the path of the free end of each of the before-mentioned selecting-stud arms. Consequently as the drum revolves these arms are lifted, and with them such permutation-bars as are in position over the arms, the bars being lifted successively owing to the arrangement of the studs on the drum. Each permutation-bar when lifted operates one or more of a number of levers which actuate a series of disks forming a multiported valve, each port of which controls the admission of air to an air-duct leading to a device which depresses a key of the linotype-machine, one such device being provided for every key.

The keyboard.—The keyboard and the mechanisms directly connected therewith are shown in Figs. 5 to 16. For convenience of description the keyboard may be divided into three sections—top, bottom, and middle—numbered, respectively, 12, 13, and 14, Fig. 5. The keys are of three kinds—syllabic, single-character, and shift keys. A syllabic key when struck gives a record of two independent characters, preferably, and in this construction a vowel and a consonant. The single-character keys give a record of a single character, and the shift-keys act on the selecting mechanism to vary both the characters recorded by the keys and the order in which these characters appear in the final record. All the keys are similar in construction, each comprising a finger-piece, which operates a valve-stem 15 by means of a lever 16, pivoted on a rod 17, the rods 17, one of which is common to the levers of each row of keys, being secured in the sides 23 of the keyboard-casing. Each lever 16 has a forked end, which embraces the valve-stem beneath its cap 18.

In front of each row of valve-stems is placed a transverse bar 19, secured in any convenient manner to the keyboard-casing. On the under side of these bars is screwed a bar 20, having slots which engage a squared portion 21 of each valve-stem to prevent the latter turning and to limit its rise under the action of the keys. On the upper side of the transverse bars are fixed plates with spring-teeth 22, which engage with collars 24 on the valve-stems to return the stems when released from the action of the keys.

A shallow compartment 25, extending over the whole portion of the keyboard occupied by the valve-stems, as seen in Figs. 7 and 10, forms the wind-box. It may be supplied with air-pressure in any convenient manner—say through the pipe 26, Fig. 10. All the valve-stems pass through the wind-box. A series of bosses 27 are provided on the upper wall of the wind-box to act as guides for the valve-stems, and conveniently these are made with a core of soft metal to act as packing for the same. Each opening for the passage of the valve-stems through the under wall of the wind-box ends in a cone-shaped valve-seat 28 to receive the conical end of its corresponding valve-stem. Each valve-seat belonging to a single character or a shift-key has one port opening into an air-conduit, while each valve-seat belonging to a syllabic key has two ports leading to different air-conduits.

As before stated, the keyboard is divided into three sections. The top section 12 and bottom section 13 are identical in construction and the description of one section will apply to both. The difference in function consists in this, that while a syllabic key in the top section gives a record of a vowel followed by a consonant a key of the bottom section gives a consonant followed by a vowel. This difference in function depends entirely on the selecting mechanism, as will be hereinafter seen. Each section comprises five transverse rows of syllabic keys, ten in each row, and six shift-keys, two placed in the middle and two on each side of the syllabic keys. The five rows are placed parallel to each other, the syllabic keys thus forming ten columns of five keys each. Beneath the wind-box are five corresponding air-conduits 29, each communicating by ports 30 with the ten valves controlled by the valve-stems of one row, each conduit ending in a pipe 31 at the right hand of the keyboard. Ten conduits 32 are placed beneath and at right angles to the conduits 29, and each communicates by ports 33 with the five valves controlled by the valve-stems of one column, each conduit 32 ending in a pipe 34, which leads to the right hand of the keyboard. Thus on the depression of any syllabic key air will be admitted into one of the conduits 29 and one of the conduits 32.

Each finger-piece of the syllabic keys is marked, as shown in Fig. 5, with a vowel and

three consonants, the same vowel being common to the keys of each row and the same consonants to those of each column. The vowel and the first consonant indicate the two characters normally recorded by that key. The vowel-records given by the keys are never altered. Shift-keys are provided to vary the consonants. Two shift-keys 35 are provided, either of which when depressed along with a single syllabic key gives a record of the vowel and the second consonant marked on that key, or if struck simultaneously with two syllabic keys records the second consonant of the first key of the chord, the second key recording normal. Two shift-keys 36 are provided, which operate in the same manner as the shift-keys 35, but give the third consonant in the record in place of the second. These keys are in duplicate merely for convenience in fingering. The two valve-stems operated by keys 35 control the admission of air to conduits 37 38, which end in a common pipe 39, and similarly the keys 36 control conduits 40 and 41, ending in a common pipe 42. A shift-key 43 is provided, which when struck simultaneously with two syllabic keys makes a record, giving the second consonant to the second key of the chord. The valve-stem operated by this key admits air to conduit 44 and pipe 45.

It will be remembered that all the keys in one row admit air into the same vowel-conduit and also all the keys in one column into the same consonant-conduit. Consequently if two keys in the same row be struck simultaneously only one vowel-record is made, and similarly two keys in the same column will give only one consonant-record. Another shift-key 46 is therefore provided, which is called the "repeat" shift-key and is struck whenever the same vowel or the same consonant occurs twice in a chord, consisting of two syllabic keys in the same section. The valve-stem operated by this key admits air into conduit 47 and pipe 48, Fig. 9.

As stated above, the top and bottom sections of the board are identical in arrangement. For convenience of reference, however, in this description the shift-keys in the bottom board have an "a" added to the number used to identify them to distinguish them from the corresponding keys of the top section.

For reasons which will be readily understood when the selecting mechanism is described when a chord of two syllabic keys is struck in the same section the normal sequence in which the final record is made by the selecting mechanism is from left to right for the consonants and from the middle of the board up and down (in the top and bottom sections, respectively) for the vowels—that is to say, if the operator strikes the key "e" in the first column and the key "a" in the second column the record obtained would be "e w a h," but if the key "a" in the first column and the key "e" in the second column be

struck instead of the desired record "a w e h" the same record as before would be obtained. Since this would greatly reduce the efficiency of the apparatus, special automatic mechanism is provided which gives an indication to the recording mechanism whenever this normal order of the vowels is to be reversed, so that the record obtained, both of vowel and consonant, shall be normally from left to right in all cases. The apparatus for this purpose is carried on the left-hand wall of the keyboard-casing, a separate but identical mechanism being provided for each section, so that one description applies to both. General views of these mechanisms are given in Figs. 8 and 9 and details on a larger scale in Figs. 13, 14, 15, and 16. In front of each row of syllabic-key valve-stems and extending through the left-hand wall of the keyboard-casing is a bar (50^a 50^b 50^c 50^d 50^e, Fig. 11) with a recess 51, corresponding to each key of the row, and on each valve-stem 15 is a square pin 49, so placed that when the stem is raised by the action of its finger-piece the pin 49 is placed within its corresponding recess. The right-hand end of each bar is movably carried on a bracket 52, while the end extending beyond the casing rests on a bracket 53, being secured thereon by a pin 54 in a slot 55, so as to be capable of endwise but not of sidewise movement. The recesses 51 increase regularly in size from left to right, as shown in Fig. 11. In the end of each bar 50^a, &c., is a slot 56, in which is engaged one end of a vertical lever 57, pivoted at 58 to a bracket 59 and carrying a toothed quadrant 60 on its lower end.

Fixed on the outside of the keyboard-casing are five bellows 61, each one of which is connected to one of the vowel-conduits 29, so as to receive air therefrom, and is operatively connected by an arm 62 to one of the quadrant-levers, between its quadrant 60 and fulcrum 58. Whenever, therefore, air is admitted into one of the vowel-conduits, the action of the corresponding bellows will move the quadrant to which it is connected outward. A spring 63 returns the quadrant to normal position. Fixed in a bracket 64 is a shaft 65, carrying five sleeves. Fixed on each sleeve is a cog-wheel 66 and bevel-wheel 67, each cog-wheel gearing with one of the quadrants 60 and each bevel-wheel with a bevel-wheel 68, fixed on the end of a sleeve 69. The sleeves 69 are revolvably carried on pins 70, fixed onto the bracket 64. Underneath the sleeves 69 and carried in slots in the bracket 64, so as to be capable of endwise movement, are five rack-bars 71^a 71^b 71^c 71^d 71^e, each bar gearing with a toothed wheel 72 on one of the sleeves 69. Each rack-bar is formed in two pieces, connected by a link 73 where it extends beyond the bracket 64. These linked ends of the rack-bar rest on pins 74, fixed on a bracket 75, secured on the end of the keyboard-casing. The portions of the rack-bars resting on these pins are recessed, the recess ending in an abrupt cam-curve 76, so that when a bar is moved

forward it is also raised. At the end of the rack-bar 71^e is a lug 77, having a slot 78, within which is engaged a pin 79. The other end of the pin is secured in a longitudinal slot 80 in a bar 81, carried on the bracket 75 in such a manner that the pin can be moved longitudinally but not vertically. A toothed wheel 82 is carried revolubly on the pin 79 and extends across the four rack-bars 71^a, 71^b, 71^c, 71^d, so that when these bars are raised their teeth engage the teeth of the wheel. Fixed onto one end of the wheel 82 is a disk 83, having a cam-curve 84 at one point of its circumference. Each of the rack-bars 71^d, 71^e, 71^b, and 71^a extends beyond the rack-bar 71^e and successively beyond each other in the order named, and at the end of each of the racks 71^d, 71^e, and 71^b is a similar arrangement of toothed wheel and cam-disk to that above described. Resting normally on the circumference of the disks 83, which may be grooved to receive it, as shown in the figures, is a bar 85, pivoted at each end to a link 86, these links being carried on pins on the bracket 75. Normally the cam-disk is in such a position relatively to the bar 85 that its cam-curve is just in contact with the bar, as shown in Fig. 13. Resting on the bar 85 is the short arm 87 of a bell-crank lever, pivoted at 88 to a pin fixed on the bracket 75. The longer arm 89 of the lever is widened out, forming a flat plate, of which one face engages the flat end of an air-conduit 90, so as to make an air-tight joint therewith while readily reciprocating over the same. A spring 109 holds the short arm of the lever pressed against the bar 85. In the arm 89 is a hole 106, connected by a flexible pipe 108 either with the keyboard wind-box or with the source of compressed air, and in the end of the conduit 90 is a hole 107, so placed that when the bar 85 is raised by the cam on the disk 83 and shifts the lever-arm 89 the two holes 106 and 107 coincide, and air is admitted to the conduit 90. This conduit ends in a pipe 108, which is assembled with the other air-pipes leading from the keyboard in the box 10. Both the mechanisms are shown in plan in Fig. 9, from which it will be seen that the top-section conduit 90 is carried along the back of the keyboard-casing, while the conduit for the bottom section (numbered 90^a to distinguish it from the top one) is carried within the casing toward the front of the keyboard.

55 The action of each mechanism is as follows: When one syllabic key is struck and air consequently admitted into a vowel-conduit, the bellows corresponding to that conduit is dilated and one rack-bar and the cog-wheel 60 connected to it are moved forward; but the other rack-bars not being raised the wheel is not rotated, but simply carried forward, and if the raised rack engages with the other cog-wheels it rotates them, so that the cam-curve 65 on the disk 83 is moved away from the bar 85, which is therefore not raised, and no air is admitted to the conduit 90. The same

thing happens if two keys be struck in the same row. If, however, two keys be struck in different rows, two rack-bars are moved 70 forward. It will be remembered that the recesses in the bars 50^a 50^b 50^c 50^d 50^e increased in length from left to right and that the pins on the valve-stems engaged in these recesses when their corresponding finger-pieces were 75 struck. Consequently the length of endwise travel possible to each bar depends on the column in which the valve-stem operated is placed, and the travel of the rack-bars it is plain from the before-given description 80 depends on the travel of its corresponding bar. If therefore two keys in the same column are struck simultaneously, although two rack-bars are raised, they both travel forward the same distance and the cam-disk does not act. 85 If also two keys be struck in different columns and rows, but in the normal order of vowels—that is, the key in the column most to the left is also in a row nearer the middle of the board than the other key—the cam-disk does not act. To give an example, if the finger-pieces corresponding to the valve-stems marked *e* and *a* in Fig. 11 be struck simultaneously the bar 50^e will travel a less distance than the bar 50^a and the rack-bar 90 71^e, Fig. 13, a less distance than the rack-bar 71^d, and the cam-disk will not act; but if two finger-pieces be struck in the abnormal order for the vowels—for example, those corresponding to the valve-stems *a'* and *e'*, Fig. 100 11—the bar 50^e will now have a greater travel than the bar 50^d. Both rack-bars 71^e and 71^d will move forward and the rack-bar 71^d engages the toothed wheel carried by the bar 71^e. The bar 71^d, however, stops before the 105 bar 71^e, and as the former is still engaged with the toothed wheel this will be rotated in the direction of the arrow in Fig. 13, the cam 84 will raise the bar 85, the arm 89 will be shifted, and air will be admitted into the 110 conduit 90, giving an indication to the recording mechanism, as will be hereinafter explained. When a chord is struck either in the top or in the bottom section, the characters called for are recorded from left to right, 115 and when a chord is struck consisting of a key in each section the top-section record is normally selected before the bottom. It is convenient that the operator should be able to reverse at will either of these arrangements, 120 and for this purpose an air-conduit 91 is provided to operate the necessary recording and selecting mechanism. This air-conduit might be controlled by a shift-key, preferably as shown in Figs. 7 and 9. Its valve is 125 operated by a pedal or footpiece 92. Air is admitted to the conduit 91 from an extension 93 of the wind-box through a valve-seat and conical-ended valve-stem 94, similarly constructed to the valves and stems of the finger-keys. The valve-stem 94 is pivoted to an arm 95 on a rocking shaft 96, carried in bearings on brackets 97, fixed on the casing of 130 the keyboard. Carried on a pin 98, fixed on

the wall of the keyboard-casing, is a cam-wheel 99, against which is pressed the free end of an arm 100, fixed on the rocking shaft 96. The cam may be operated by the pedal 5 in any of the known methods—say by lever 101, groove-wheel 102, and spring-held cord 103, as shown in Figs. 7 and 9.

The middle section of the board comprises eighteen single-character keys, six shift-keys, 10 and a space-key. Ten of the single-character keys are marked with three consonants, the first of these being the character recorded if a key be struck alone, the second if one of these keys be struck along with 15 either of the shift-keys 35^b, and the third if with one of the shift-keys 36^b. These shift-keys 35^b 36^b are duplicated, as in the case of the similar shift-keys in the other sections, merely for convenience in operating, the conduits 20 controlled by their valve-stems uniting in common pipes numbered 110 and 111, respectively. (See Fig. 9.) The eight other single-character keys record when struck the characters marked on them in Fig. 5. The 25 two other shift-keys are labeled "Caps" and "Numerals and stops." The capital shift-key may be struck along with either a single key or a chord of keys of any section or sections; but when struck as part of a chord 30 only the first character selected will be a capital, the rest of the characters called for by the chord being small letters. The "numerals and stops" shift-key is operated along with any other key of the board to which the 35 desired character may be assigned. It cannot, however, be used as part of a chord, or, if so used, only the first character recorded will be a numeral or stop, the rest of the chord-record being characters normally called 40 for by the key struck.

The space-key may be struck singly or as a chord with one or more other keys. If struck as part of a chord, it always appears at the end of the record.

45 All the valve-seats 28 controlled by the valve-stems operated by the keys of the middle section have but one port, only one conduit being controlled by each key. These conduits may be arranged in any convenient 50 manner, a desirable arrangement being shown in the figures; but it is not necessary to more particularly describe them, as their arrangement is purely arbitrary.

In the foregoing description I have spoken 55 of "top," "bottom," and "middle" sections of the keyboard. In Fig. 45 are shown diagrammatically the connections between the valve-seats of the keyboard wind-box and the bellows 222 of the recording mechanism herein- 60 after described. The bottom-section connections being identical in arrangement with those of the top section are omitted. Although I prefer this arrangement of finger-pieces, as shown in Fig. 5, the position of the 65 sections of the board relatively to each other, as well as the arrangement of the individual finger-pieces in each section, is purely arbit-

rary and may be changed at will, since it is plain that the arrangement of air conduits and pipes may be varied to any reasonable 70 extent. An alternative arrangement is shown in Fig. 6, in which the sections 12 and 13 are placed side by side and the section 14 centrally below them.

All the pipes leading from the air-conduits 75 are assembled in the box 10 and carried therein to the recording portion of the apparatus. There are sixty-four of these pipes in all—viz., nineteen for the top section, nineteen for the bottom section, twenty-three for the 80 middle section, two for the automatic vowel-reversal mechanism, and one for the pedal or reversal key.

The recording mechanism.—The two principal features of the recording mechanism are 85 the record-drum and the permutation-bars.

The record-drum, Figs. 17 and 18, is a hollow cylinder having a number of slots 201 in its circumference parallel to its axis. In each of these slots is a number of studs 202, hereinafter called "record-studs," engaged in the 90 slots, so as to be capable of movement along them. Fig. 18^a is a perspective view of one of these record-studs detached.

The record-drum may be constructed in any 95 convenient manner. A preferred form is shown in Figs. 17 and 18 and comprises two ends, each having a central boss 203, bored to receive a shaft, and a circumferential flanged ring 204, connected to the boss by arms 205. The two ends are connected together by slats or bars 206, fixed onto the flange of the rings 204 by countersunk screws 207, the slats being placed a sufficient distance apart to form the stud-slots 201.

The record-drum is fixed onto a shaft 208, revolvably carried in bearings in the standards 6 and 7, and extends across the front of the apparatus between the said standards.

The record-drum is inclosed in a casing 110 hereinafter called the "record-drum shield." Extending across the whole length of the shield parallel to the axis of the record-drum is a single slot 210, and it is also provided with a series of circumferential slots at right 115 angles to the axis of the drum in number double the number of the record-studs contained in one slot in the record-drum. Each alternate slot 211 extends entirely around the shield from one edge of the longitudinal slot 120 to the other. These I call "inoperative slots," and normally the record-studs are engaged in these slots. The remaining slots 212 start from the lower edge of the longitudinal slot 210, but shortly before reaching 125 the upper edge of said slot they merge by a gradual curve, each into the adjacent inoperative slot to its right, as shown in Fig. 17. A convenient form of construction of the shield is shown in Figs. 17 and 18 and 130 comprises two end disks 213, with central bosses bored to form a working fit with the bosses on the record-drum ends, or instead of disks heavy rings may be employed. The

body of the casing consists of metal rings 214, with lugs 215 bored to receive long bolts 216, on which the lugs are strung, collars 217 being placed between each lug to keep the 5 rings apart and form the slots. Corresponding lugs 218 are provided on the end disks and the whole held together by nuts 219 on the bolts 216. Offsets 220 are provided on the end disks, to which are secured bracket- 10 arms 221, Fig. 3, bolted onto the standards 6 and 7, so as to hold the shield rigidly secured to the same.

The record-drum is revolved with an intermittent motion, so that each row of studs is 15 brought to a standstill when central in the longitudinal slot 210 of the shield. The mechanism for effecting this is shown in Figs. 2, 3, 21, 21^a, 21^b, and 23. A ratchet-wheel 224 is fixed on the shaft 208, the pitch of its teeth 20 corresponding to the rows of studs on the record-drum. Revolubly carried on the same shaft, contiguous to the ratchet-wheel, is an arm 225, carrying on a pin a pawl 226, held in engagement with the ratchet-wheel teeth 25 by a spring 227. A collar 228 keeps the arm from side movement on the shaft. The assembling-drum 400 is fixed on a shaft 426, carried in bearings 427 on the standards 6 and 7. This shaft is constantly revolving 30 while the apparatus is working, and keyed thereon between the assembling-drum and the standard 6 (at the right hand of the apparatus) is a disk 229, with a cam-groove 230 on its face. Pivoted at one end on a pin 231, 35 fixed on the standard 6, is an arm 232, having a lug 233, which carries a pin 234, engaged in the cam-groove. The cam-groove is shaped as shown in Fig. 21, comprising a number of similar curves, so that the arm 232 is vibrated 40 several times (eight as shown in the figure) during one revolution of the disk. Pivoted in a slot in the free end of the arm 232 is a bar 235, guided so as to reciprocate in an approximately vertical direction by pins 236, 45 engaged in slots 237. In the front edge of the bar is a recess 238. Carried in a recess in a block 239, formed with or secured onto the standard 6, is a short bar 240, with a head 241 extending beyond the block. Nor- 50 mally the bar lies at the bottom of the recess, with its head touching the block, as shown in Fig. 21, the recess being formed with guides, so that the arm is held rigidly against side movement, but is capable of both 55 up-and-down and back-and-forth movement therein. On one wall of the recess are a projection 242 and a spring 244. The arm is pro- 60 vided with a pin 243. The head 241 is pro- 65 vided with a tooth 245, placed opposite to the recess 238 in the bar 235, and has pivoted to it one end of a link 246, the other end of which is pivoted to the free end of the pawl-arm 225, described above. Fixed on the under side of the block 239 is a bellows 247, 70 which receives the air to operate it through pipe 248, controlled by valve 250, Fig. 19. This valve is operated by mechanism con-

trolled from the keyboard, to be hereinafter described. Carried on a pin 249 is a bell-crank lever 251, one arm of which engages 70 the under side of the bellows, while the other arm engages the end of the arm 240. The operation of this mechanism is as follows: Normally the arm 240 is in the position shown in Fig. 21, lying in the bottom of the recess 75 and with its pin to the left of the projection 242. On air being admitted through the valve 250 the bellows, expanding, operate the bell-crank lever, which pushes the arm 240 forward, so that the tooth 245 comes against the 80 constantly-reciprocating bar 235 and on that bar reaching its lowest position, as shown in Fig. 21^a, enters the recess 238. The arm is immediately carried up by the reciprocating bar into the position shown in Fig. 21^b, and by 85 means of the link 246 raises the arm 225 on the record-drum shaft, so that the pawl 227 moves the ratchet-wheel 224 the pitch of one tooth, and thereby revolves the record-drum, bringing a fresh row of record-studs into the 90 longitudinal slot of the shield. Directly the arm 240 is raised its pin 243 is brought under the tension of the spring 244; but the pin is held from back movement by the projection 242 until the arm has reached the top of the 95 recess and the pin is clear of the said projection, when the action of the spring on the pin forces the arm back, withdrawing the tooth 245 from engagement with the reciprocating bar, and the arm falls by its own weight (or 100 a spring may be provided for this purpose) back into the normal position shown in Fig. 21. The mechanism for shifting the record-studs from inoperative to operative position is shown in Figs. 19 and 20. 105

Above the record-drum, extending between the standards 6 and 7, to which it is fixed, is a bar 252, having a number of pins 253. Carried on each pin, so as to be capable of both a rotatory and an up-and-down movement 110 thereon, is an arm 254. These arms are equal in number to the record-studs in one row of the record-drum, and the lower end of each arm is provided with a fork 255, which embraces one of the record-studs when a row of 115 studs is arrested in the longitudinal slot of the shield. The end of each arm where pivoted on its pin 253 is held between the forked end of an arm 256, the other end of which is fixed on the hinged flap of a bellows 222. 120 These bellows are fixed onto one side of a plate 257, which forms part of a frame 223, extending between and fixed to the standards 6 and 7, and in the said plate are two holes 259 and 260, opening into each bellows, 125 forming the inlet and outlet, respectively, for the air operating them. To each of the inlet-holes 259 is connected one of the pipes carried in the box 10, coming from the air-conduits of the keyboard. 130

It will be remembered that there are sixty-four air-pipes leading from the keyboard. For a reason which will be understood when the selecting mechanism is described there

are sixty-six record-studs and sixty-six bellows to operate them, each of the pipes leading from the repeat shift-keys 46 and 46^a being branched, so as to operate two bellows. A 5 reciprocating plate 261 is carried in the frame 223, so as to form an air-tight joint with the plate 257. It is provided with a slot 262, through which the air-pipes pass, and with holes 263, one for each bellows, so placed that 10 when the plate is reciprocated these holes correspond with the outlet-holes 260 of the bellows, while normally these latter are closed by the plate. The bellows are so placed relatively to the record-drum that when collapsed 15 their hinged flaps and the rods 256, carried thereby, hold the arms 254 raised on their pins, so that their forked ends 255 stand clear of the record-studs. When, however, a key is operated and air thereby forced into a bellows, the corresponding arm is pressed down 20 against the record-drum, so that its forked end embraces a record-stud. Beneath and extending across all the arms 254 is a bar 264, carried in brackets 265 on the bar 252. The 25 bar 264 is reciprocated by a lever 266, one end of which is pivoted on the bar 252, while the other end engages a cam-disk 267, revolubly carried on the record-drum shaft 208, the lever having a pin 268, which engages in a slot 30 in the bar 264. The bar 264 is provided with a number of pins 258, one for each arm 254, so placed that when the lever 266 is in the position shown in Fig. 19—that is, engaged with the bottom of a depression of the cam-curve— 35 each pin is touching its corresponding arm. The pins are of a height to engage any arm when depressed by its corresponding bellows-rod, but to pass under free of the same when in its raised or inoperative position. The 40 cam-curves are of such a pitch that when the lever engages the highest part of a curve the teeth swing the arms 254 to the left (looking at Fig. 19) a distance sufficient to bring its forked end (and consequently the record- 45 stud engaged thereby) opposite an operative slot 212 of the record-shield. The cam-disk 267 is constantly revolved from the shaft 426 through a short counter-shaft 269, carried in bearings on the front of the standard 7 by pulleys 270 271, belted to pulleys 272 and 273 on the shaft 426 and record-drum shaft 208, respectively, Figs. 3, 4, and 19.

It is necessary that the placing of the record-studs opposite their operative slots should 50 synchronize with the stoppage of the record-drum and be immediately followed by an onward movement of the same, and it will be remembered that the movements of the drum are controlled by the air-valve 250. The mechanism for opening and closing this valve is 55 operated by the arms 254 as follows: Beneath the bar 264 is a second bar 274, capable of reciprocation in brackets 275 on the supporting-bar 252. This bar 274 is also provided 60 with pins 276, one for each arm 254, which when the arms are in line with the inoperative slots 211 of the shield are in contact with

the same, but on the opposite side to the pins on the bar 264. These pins, moreover, (for a purpose to be hereinafter described,) engage the arms 254 when raised from the record-drum as well as when engaged with the record-studs. Pivoted on a bracket 277 is a latch 278, having a catch 279, which normally stands to the left, Figs. 19 and 20^a, of an offset 70 75 80 85 90 95 100 105 110 115 120 125 130 135 280 on the bar 274, the offset being shaped with a curve on one side, which acts as a cam to raise the catch 279 against the tension of a spring 281 when the bar 274 is moved to the left. The catch is also adapted to be raised by a curved arm 282, fixed on a rocking spindle 283, carried in a bearing 284, depending from the bar 252. The spindle is rocked by a lever 285, actuated by a cam-disk 286, fixed onto the record-drum shaft 208. The circumference of the disk is formed with a number of equal curves, the distance between the highest points of which corresponds to the distance traversed by the record-drum at each intermittent movement of the same, and when the drum is at rest the shorter or actuating arm of the lever rests on the highest point of one of the curves, as shown in Fig. 20. The longer arm of the lever reciprocates the plate 261 (which has the exhaust-openings for the bellows 222) by means of the bell-crank lever 287, connected to a pin 289, formed on the end of the plate, and to the arm 285 by a twisted link 288. The valve 250 is carried on a bracket 290, fixed on the standard 6. It is connected with the source of compressed air by a pipe 291, which opens into a chamber having a port with a conical valve-seat to receive the pointed end of a valve-stem 292, which passes through one end of the valve-box. The valve-stem is pivoted to one end of a short lever 293, which is pivoted at 294 to an arm on the bracket 290 and has its other end pivoted in a slot 295 in the end of the bar 274. The valve-stem point is held normally pressed against the valve-seat by a spring 296, fastened on the bar 274 and bracket 275. The pipe 248, before referred to, connects the port with the bellows 247 of the record-drum-actuating mechanism.

As described above, whenever one or more keys are struck on the keyboard air is admitted to the corresponding bellows, and the corresponding rod or rods 256 cause the corresponding arm or arms 254 to engage a record stud or studs. At the same moment each of such operated arms engages a pin 258 on the constantly-reciprocating bar 264 and is moved to the left, Fig. 19, bringing its record-stud opposite an operative slot. Owing to the engagement of the arms 254 with the pins 276 of the lower bar 274, this bar is also moved to the left and pulls the valve-stem off its seat, starting the record-drum. This, however, does not take place until just before the bar 274 has completed its movement owing to the lever 293 being pivoted in the slot 295. When the bar 274 is moved to the left, it carries the offset 280 to the left of the

catch 279, which thus prevents the immediate return of the bar 274, this being necessary in order that the arms 254 should not be swung back to normal position before they are lifted 5 from engagement with the record-studs. As the record-drum moves, the lever 285, following the curve of the cam 286, reciprocates the plate 261, allowing the air to escape from the bellows and the arms 254 to be raised above 10 the record-studs. The lever 285 also rocks the spindle 283, and the curved arm 282 thereupon releasing the catch from the offset 280 the bar 274 flies back under the tension of spring 296, closing the valve 256 and by its 15 teeth 276 swinging the arms 254 back to normal position—that is, in line with the inoperative slots.

The permutation-bars.—Placed in a row above and parallel to the axis of the assembling-drum 400 and to the back of the record-drum are the permutation-bars, numbered 301 to 319, according to their special function. There are sixty-eight of these bars, one corresponding to each of the record-studs, 25 and two extra bars, for a reason hereinafter explained. The bars are hung on a shaft 320, fixed in the standards 6 and 7 by nuts 321, each bar being provided with an opening 322, circular at the top to fit the shaft, but 30 deeper than the diameter of the shaft, allowing the bars both to swing on the shaft and to be raised vertically. Between each bar (with the exception of the two extra bars before referred to) and movably carried on the 35 same shaft is a curved arm 323, having a pin 324, which engages the back edge of the contiguous permutation-bar. Collars are likewise provided on the shaft 320 between the bars and the curved arms to space these the 40 proper distance apart. The curved arms are so placed that each arm is coincident with one of the operative slots 212 of the record-drum shield, and between each curved arm and the record-drum, and therefore engaged 45 within each operative slot of the shield, is a distance-piece or latchet 112. These latchets are slung on a common spindle 113, fixed in arms 114 214^a, Figs. 2, 22, and 23, one at each end of the record-drum, and are normally 50 in the position shown in Fig. 22—that is, approximately in a horizontal line with the axis of the record-drum and resting on the same within an operative slot of the shield. Whenever a record-stud has been placed in 55 an operative slot and brought under its corresponding latchet, the stud will push out the latter, which will remain out as long as the stud remains beneath it. These two positions of the latchets are shown in Fig. 60 22. Each curved arm 323 is held in contact with its corresponding latchet by its corresponding permutation-bar, the permutation-bar being pulled back and held in contact with the pin 324 of the arm by a spring 325, 65 one end of each of these springs being fastened to a permutation-bar, and the other to a common rod 326, extending between the

standards 6 and 7. The position in which the permutation-bars and curved arms are held by the springs 325 therefore depends on the record-latchets, and they are so placed relatively to the record-latchets that when these are in their inoperative position—that is, resting on the face of the record-drum—the permutation-bars are also in their inoperative 75 position, slightly inclined from the perpendicular, as shown in Fig. 2. When any latchets are pushed out by their record-studs, the corresponding permutation-bars are swung out into a perpendicular position, as 80 shown in dotted lines in Fig. 35, this being their operative position. Both positions of the permutation-bars are shown in Fig. 35.

It will be remembered that the movements of the record-drum are occasioned by and 85 synchronous with the depression of a key or chord of keys on the keyboard, and from the above description it is seen how the permutation-bars called for by the key or chord of keys are placed in operative position for the 90 selecting mechanism to obtain the desired final record. As will be seen when this latter mechanism is described, it is necessary that the permutation-bars placed in-operative position by one movement of the record-drum 95 should remain in that position during one complete revolution of the assembling-drum and during one revolution only. Although this drum is revolved at a speed with which it is impossible for an operator to keep pace 100 for any length of time, it is possible for him to strike two or even three chords in succession at a greater speed than that at which the assembling-drum revolves. If then the latchets were held on fixed arms, there might 105 be a danger of a line of record-studs being moved from beneath the latchets before all or any of the permutation-bars had been operated. Moreover, the studs might remain under the latchets for longer than one revolution 110 of the drum, when the record would be repeated. It is necessary, therefore, that the latchets forming the record should be held in operative position—that is, resting on studs—during one complete revolution of the assembling-drum and during one revolution only. 115 The following mechanism is provided for this purpose, Figs. 22, 23, 23^a, 23^b, 23^c, 23^d, and 23^e: It will be remembered that the latchets 112 are carried on a spindle 113, held in two 120 arms 114 and 114^a. The arm 114^a, to the left of the record-drum, is revolvably carried on the record-drum shaft 208, as shown in Fig. 2. The arm 114, to the right hand of the record-drum, is fixed onto a sleeve 115, 125 carried in a bearing in the standard 6, the sleeve forming the bearing in which the record-drum shaft 208 revolves. Outside the standard 6 the sleeve is provided with a collar 116, having two flanges 117 118, forming 130 a groove within which is engaged the forked end 119 of a lever 120, pivoted at 121 in a bracket on the standard 6. The short arm of the lever is furnished with a nose 130, which

is held by a spring 131 against a cam-wheel 132, carried on a pin 133 on the front of the standard 6. The collar 116 is secured onto the sleeve by a feather 122, so as to be capable of endwise movement on the sleeve, but not of rotatory movement thereon. Placed side by side and secured fixedly together and onto the record-drum shaft 208 are two ratchet-wheels 128 129, the teeth of which are of equal pitch, but placed intermediate the one of the other, and the distance from the tooth of one wheel to the adjacent tooth of the next corresponds to half the distance between the rows of studs on the record-drum. The collar-flange 118 has an offset 134, in which is fixed a pin 135, provided with a catch 136. The catch is the same width as one of the wheels 128 129, and it is held constantly in contact with a tooth of one of these wheels by a coiled spring 125. This spring has one end fastened onto a pin 127 in the standard 6, its other end being connected to the free ends of a flexible band 126, the other end of which is secured to the collar 116. Consequently at each movement of the shaft 208, on which the record-drum is fixed, the sleeve is also carried around against the tension of the spring, and the arm 114 and latches move with the record-drum. The cam-wheel 132 is provided with a number of depressions of such a depth that when the nose of the lever enters the same the collar is moved endwise, so as to cause the catch to pass from whichever one of the wheels 128 and 129 over which it happens to be positioned to the other wheel, the collar and sleeve consequently flying back under the tension of the spring 125 until the catch 136 engages a tooth of the wheel over which it is now placed and the latches fly back for half the distance between two rows of record-studs. The latches will therefore be carried around with the record-studs so long as the lever 120 is not shifted, but will fly back every time the lever shifts the collar-catch from one wheel 128 or 129 to the other.

The movements of the cam 132, which vibrates the lever 120, are controlled from the assembling-drum by the following mechanism: As before stated, the assembling-drum 400 is provided with selecting-studs, which as that drum revolves pass under and raise the free ends of short pivoted arms, called "selecting-stud arms." There are seventy-one of these arms, numbered 350 to 373^a, and they are carried on a spindle 374, fixed in the standards 6 and 7. The last two, 373 and 373^a, on the right hand, operated by the selecting-studs 425 and 425^a, are employed to operate the cam 132. Revolvably carried on the spindle 374, between the selecting-stud arm 373^a and the standard 6, is a sleeve 376, having a curved arm 377 on the end nearest the standard 6 and an offset 476, with a hole 477 therein, on the other end. A vertical link 137, carried in a guide in a bracket 138 on the standard 6, operatively connects the curved

arm 377 with a short arm 139, pivotally carried on the pin 133. This arm carries a spring-pressed pawl 140, which engages the teeth of a ratchet-wheel 141, fixed on the cam-wheel 132, the pitch of the ratchet-wheel teeth being equal to the distance between a depression and the center of the adjacent raised portion of the surface of the cam 132. The selecting-stud arm 373^a is carried on a short sleeve 478, and its free end has a depending lug 375, which normally rests on the surface of the assembling-drum 400. The sleeve 478 is provided with a vertical offset 485, having a hole 486, and also with a short vertical arm 479, having a lug 480, which extends over the offset 476 of the sleeve 376 and has a hole 481, coincident with the hole 477 of that offset, and also a slot 482, in which is engaged a short spindle 483, carrying a pin 484, movably carried in the hole 481. This pin is held in position by the spindle 483, engaging in slots in the forked ends of an arm 487, fixed on a rocking sleeve 488, which is carried on a pin 489 on the standard 6. The sleeve 488 has a second arm 490, operatively connected by a link 491 to one arm of a bell-crank lever 492, carried on a pin 493 on the standard 6. The other arm of the bell-crank lever has a curved cam-surface 494, which bears against a pin 495, screwed in the spindle 113, which carries the latches 112. The cam-surface 494 is so placed relatively to the pin 495 that when the latches are in normal or highest position, as shown in Fig. 23^a, the pin 495 is at the top of the cam curve. A spring 496, connected to the arm 490, and a pin 497 hold the cam-surface constantly against this pin 495 until (as the latches are lowered) it has reached the bottom of the curve, when the short arm on the bell-crank comes against a stop 517, fixed on the standard 6. Whenever, therefore, the spindle 113, carrying the latches, is lowered, the bell-crank raises the arm 490 and lowers the arm 487, engaging the pin 484 in the hole 477 and locking the stud-arm 373^a and the cam-operating rocking sleeve together. The selecting-stud arm 373, placed to the left of the arm 373^a, also has a lug 375, normally resting on the surface of the assembling-drum and is carried on a boss 498, which has a short vertical arm 499, with a lug 500 extending over the offset 485 of the selecting-stud arm 373^a. The lug has a hole 501 coincident with the hole 486 in the offset 485 (when the lugs 375 of both arms are resting on the surface of the assembling-drum) and a slot 502, in which is engaged a short spindle 503, carrying a pin 504, movably carried in the hole 501. The upper portion of the pin 504 is lessened in diameter and ends in a short cross-head 505. The pin 504 is held in position by the spindle 503, engaging in slots in the forked end of an arm 506 on a boss 507, revolvably carried on the pin 489, which carries the rocking sleeve 488, already described. The boss has a short vertical arm 508. The arm 508 is yieldingly connected by

the spring 510 to a similar arm 511 on the rocking sleeve 488, and this latter arm is provided with a pin 512, which engages the edge of the arm 508 when the two arms are in normal relative positions, as shown in Fig. 23^a. Whenever, therefore, the action of the bell-crank lever lowers the forked arm 487, the spring 510 tends to lower the arm 506, and when the arm 487 is raised the pin 512 raises the arm 506 with it. Fastened onto the under side of the bracket 221 and placed directly over the pin 504 is a plate 524. The plate is shaped, as shown in Fig. 23^f, so as to allow the cross-head 505 of the pin 504 to pass up in front of the plate. Placed in front of the plate, so as to support the cross-head, is a fork 525, carried on an arm 526 on a boss 527, revolvably carried on the boss 498 of the selecting-stud arm 373. The fork 525 has a pin 514, which is held pressed against a pin 513, depending from the plate by a light spring 528, and the plate is slotted to allow the fork to be pressed back by the cross-head 505 when the pin 504 is raised by the forked arm 506. Fixed on the assembling-drum in the path of the lug 375 of the stud-arm 373^a is a selecting-stud 425^a, and a selecting-stud 425 is placed in the path of the lug of the stud-arm 373, the studs being so placed on the drum that at each revolution of the same the stud-arm 373^a is rocked before the stud-arm 373.

It must be borne in mind that the assembling-drum is constantly rotating and that the record-drum is turned a distance equal to that between two adjacent rows of its record-studs whenever one or more of these studs in one row have been placed in operative position by the depression of a key or chord of keys on the keyboard. When no key is depressed, the latches are held by their arms 114 114^a, resting in the operative slots of the record-drum shield against the surface of the record-drum midway between the row of record-studs in the longitudinal slot of the shield and the row of studs below the same, as shown in Fig. 22. As the assembling-drum revolves the studs 425^a and 425 rock the selecting-stud arms 373^a and 373; but these not being connected with the sleeves 376, through which the cam 132 is operated, no action takes place, and the latchet-arms remain stationary. If now a key or chord of keys be struck, the record-drum is moved forward, and the catch 135 of the collar 116 being engaged against a tooth of one of the wheels 128 129—say of 128, as shown in Fig. 23—the latchet-arm 114 and the latches are moved downward with the drum. In moving down, the pin 495 on the latchet-spindle 113 has been carried to the position shown in dotted lines in Fig. 23^b, freeing the bell-crank lever 492, which takes the position shown in full lines 423^b, and by its link 491 raises the arm 490 and rocks the sleeve 488, depressing the forked arm 487 and engaging the pin 484 in the hole 477 of the offset 476, thus locking the stud-arm 373^a to the sleeve 376. When now the stud-arm 373^a

passes over the selecting-stud 425^a, the sleeve 376 is rocked and the cam 132 moves the pitch of one of the teeth of its ratchet-wheel 141, vibrating the forked lever 120 and shifting the catch 135 from over the wheel 128 to the wheel 129. Under the tension of the spring 125 the catch flies back, engaging the first tooth of the wheel 129. It will be remembered that the pitch between the adjacent teeth of the wheels 128 and 129 corresponds to half the distance between adjacent rows of the record-studs. Consequently the latches fly back and are arrested when in line with the first line of record-studs in the position shown in full lines in Fig. 23^b. Consequently any latchet corresponding to a record-stud which has been placed within an operative slot will be moved out by that stud, as shown in Fig. 23^b. If no second key or chord of keys be struck, at the completion of a revolution of the assembling-drum the selecting-stud arm 373^a will be again rocked by the stud 425^a, the cam operated, and the latches fly back to the position shown in Fig. 23^a, the arm 487 being again raised and the pin 484 disengaged from the hole 477 and the selecting-stud arm and sleeve 376 disconnected. When the forked arm 487 is lowered, as above described, the spring 510 puts tension on the forked arm 488 to lower it; but the offset of the pin 504 being above the forked catch 525 the arm 488 is held up thereby, and the stud-arm 373 is not locked to the stud-arm 373^a until the former has been rocked by passing over its stud. This, it will be remembered, can only occur after the stud-arm 373^a has been rocked, owing to the relative position of the studs on the drum. Consequently when the latches are moved away from normal position or zero their first backward movement is limited to half the distance between the record-studs; but once the latches after being moved from zero have moved back again a half-pitch by the rocking of the stud-arm 373^a the stud-arm 373 is raised by its stud and the offset of the pin 504 rocked forward from off the forked catch 525. The spring 510 now acts to lower the forked arm 506, and with it the pin 504, which immediately drops, so that its offset is below the plate 524; but this pin cannot enter the hole 486 until both stud-arms are resting on the surface of the assembling-drum, so that the stud-arm 373 has no action on the cam 132 until that revolution is completed. Both stud-arms, however, are now engaged, through their pins 484 and 504, with the sleeve 376, and two motions rapidly following each other will be given to the cam at the commencement of the next revolution. If, therefore, the operator strikes a key or chord of keys while the latches are in the position shown in 23^b, the latches will be moved forward with the drum and carried back a full pitch—that is, onto a following row of record-studs—every time the assembling-drum commences a revolution, the studs 425^a and 425

being placed before any other selecting-studs, as shown in diagram 39. Directly the latches reach their normal or zero position the bell-crank lever 492, raising the forked arms 5 487 and 506, raises both pins 484 and 504, unlocking the stud-arms from the sleeve 376, and all action on the cam ceases.

When a permutation-bar is in its operative position, its corresponding curved arm forms 10 an arc of a circle of which the axis of the record-drum is the center, so that the permutation-bars will be maintained in correct operative position irrespective of the position of the point of contact of the latchet and the 15 arm. It is not considered to be possible for an operator to strike more than two, or at most three, chords during a single revolution of the assembling-drum; but the curved arms are made long enough for six records to 20 accumulate before the latchets would be carried free of the arms.

As before stated, there are sixty-eight permutation-bars carried on the shaft 320. Twenty-two of the bars, numbered 301 to 306, 25 are placed in operative position by the action of the keys of the top section of the board; twenty-two, numbered 307 to 312, by those of the bottom section; twenty-three, 313 to 318, by those of the middle section, and one, 319, 30 the reversal-bar, by the action of the pedal. The position of the bars on their shaft 320 is shown diagrammatically in Fig. 40, those of the top section being on the left-hand side of the apparatus and the reversal key-bar 319 on 35 the extreme right.

When in operative position, the permutation-bars are actuated by being raised vertically by the selecting-stud arms, before referred to. There are seventy-one of these 40 arms, numbered 350 to 373^a, one for each of the permutation-bars, (except the repeat-bars 302^a, 305^a, 308^a, and 311^a,) and six other arms which do not actuate permutation-bars directly. Five of these, 350 350^a 351 370 371, control mechanism connected with the bars, as will be seen hereinafter, and two, 373 and 373^a, control the position of the record-drum latchets, as already described. The position of these arms on their shaft 374 is shown diagrammatically in Fig. 40. All the selecting- 50 stud arms have the following common features, as seen in Fig. 26^a, viz: a body bored to receive the shaft 374, the arm proper, and a lug 375 on the under side, which rests on the surface of the assembling-drum. They 55 vary, however, in other points, according to their special functions, as will be seen when the particular devices operated by them are described in detail. Their free ends are in a line under the centers of the permutation-bars when these are in operative position.

With the exception of the repeat-bars, two of the automatic vowel-control bars, and the reversal-bar, each permutation-bar when 60 lifted opens a port in a valve 450, Figs. 1, 2, and 4. This valve has as many ports as there are keys in the linotype-machine it is in-

tended to operate a pipe 453, leading from each port to the particular lino-key it is designed to operate.

70 *Valve.*—The valve and the mechanism operating it are shown in detail in Figs. 36, 37, 37^a, and 37^b.

The valve comprises ten rings (marked 450^a to 450^j) movably held between two covers 451 and 452. The cover 452 is a ring having an annular recess 454. The ring is carried by arms on a boss 456, bored to receive a pin 457, to which it is rigidly secured. The pin 457 is fixed onto a rear extension of the standard 80 6, Figs. 1, 2, and 4. A pipe 466 connects the recess 454 with the supply of compressed air. The cover 451 likewise consists of a ring carried by arms on a boss 458. This boss, however, is secured on the pin 457, so as to 85 be capable of endwise, but not of rotatory, movement thereon by a feather 459. The ring is provided with a number of holes arranged in two circles to receive the pipes 453, leading to the linotype-machine keys. Between the two covers are the ten rings, forming the valve proper. The inner face of the cover 452 and one face of each valve-ring are provided with two circular offsets 455 and the inner face of the cover 451 and the other 95 face of each valve-ring with corresponding grooves to receive the same. The surfaces of the cover and valve rings are faced, so as to make air-tight joints with each other, and are held in contact by the spiral spring 460, 100 placed between the cover 451 and a collar 461 on the pin 457. Each valve-ring has an offset 462, which is in contact with a bar 463, fixed on the standard 6, when the ring is in its normal or inoperative position. Each 105 valve-ring 450^a to 450^j is provided with port-holes arranged in two circles corresponding to those in the cover 451 and falling within the recess 454 of the cover 452. The valve-ring 450^j has only four port-holes on each 110 circle, a continuous slot being provided, so that the port-holes of the ring 450^j are open to the recess of the cover 452. The arrangement of these port-holes is shown diagrammatically in Fig. 38, which may be taken to 115 represent sections taken through each circle of ports laid out flat.

As represented in the diagram, the valve is in its normal or inoperative position, and in no case is complete communication established between the recess of the cover 452 and the port-hole pipes 453 of the cover 451. The holes in the various valve-rings are, however, so arranged that by rotating one or two or more rings a distance equal to half 125 the distance between the port-holes in the cover one through-passage may be formed between the recess 454 (which through the pipe 466 is kept constantly supplied with air) and any one of the cover port-holes. The 130 port-holes allotted to the vowels and certain consonants are correspondingly lettered in the diagram Fig. 38, and taking the letter "e" as an example it will be seen that by

shifting the ring 450^a a complete connection is made between the recess and the cover port-hole allotted to that letter, while all other passages are still held closed, or taking the letter "h," it will be seen that three rings 450^a , 450^b , and 450^c must be simultaneously shifted to establish through communication. As will be seen from the diagram, part of the outer circle of ports is allotted to small letters and the corresponding ports in the inner circle to capitals, the numerals and stops being divided between both.

It is of course evident that the allotment of and arrangement of port-holes are arbitrary and purely a matter of convenience.

In the arrangement here shown the five rings 450^a to 450^e are allotted to the small characters (the vowels and the consonants normally recorded by the finger-pieces of the keyboard) and the space-key, the four rings 450^f to 450^i being joined to these rings for the other characters, the ring 450^f for the second set of consonants, 450^g for the third set, 450^h for the capitals, and 450^i for the numerals and stops. The ring 450^j gives effect to the automatic vowel-control mechanism described in connection with the keyboard, and as may be seen by looking at the diagram, its function when shifted is merely to close the vowel-ports.

The mechanism for shifting the rings is as follows: Carried in the standards 6 and 7 behind the permutation-bars are ten rocking shafts 330 to 339, arranged in two rows one above the other. Rigidly secured to or formed integral with each shaft is an arm, the free end of which engages in a recess 467 in one of the valve-rings, so that rocking the shaft will shift the corresponding ring. These arms 327 on the under row of shafts are placed above their shafts, the arms 328 of the upper row of shafts below them, so that the ten arms are all in the same horizontal line. The arms 327 engage the five valve-rings 450^a to 450^e , the arms 328 the remaining five 450^f to 450^j . Each arm is provided with a spring 464, the tension of which normally holds the nose of the arm against the upper edge of the recess 467 and the offsets 462 of the valve-rings 50 against the bar 463.

As before stated, the valve is operated by the vertical movement of the permutation-bars, and to enable the shafts 330 to 339 to be rocked by these bars they are provided with arms 329, the free ends of which have pins 465 to engage with an offset 340, placed on one side of the bar. The position of this offset will vary according to whether the engaging arm is in the upper or lower row.

It is of course necessary that the length of travel of all the valve-rings should be identical, while from the varying relative positions of the bars, shafts, and valve-rings the arms vary in length. To equalize the action of the arms on the valve-rings, the slots 467 may be made of varying depths, so as to engage the arms during part only of their move-

ment. The pins on the arms 329 also are made to engage the offsets 340 on either side of the center line of the permutation-bars, according to the length of the arms for the same purpose, the offsets also being placed slightly on an incline, so as to engage the arms for the whole or only a portion of the vertical rise, according to the position of their pins relative to the center line of the bar.

The permutation-bar 318 (shown in Figs. 36 and 37) is the one controlled by the shift-key "Caps" of the keyboard. It operates the valve-ring 450^h , and the arm 329, engaging its offset 340, is fixed on the rocking shaft 338. The five valve-rings 450^a to 450^e return to normal position directly their operating permutation-bars are lowered; but for a reason which will be understood when the selecting mechanism is described it is necessary that each of the other five rings 450^f to 450^j should remain in the position in which they are placed by the lifting of a permutation-bar until one of the five disks 450^a to 450^e has also been shifted. The following mechanism is provided for this purpose:

Each of the arms 327 is provided with a depending lug having a nose 340 to engage a common bar 341, carried by arms 342 on a sleeve 343. The sleeve 343 is movably carried on a spindle 344, fixed to the standard 6, and is provided with arms 345, which normally rest on a bar 346, carried by arms 347 on a second sleeve 348. The sleeve 348 is capable of rotation on a spindle 349 and is provided with five catches 378. The sleeves 343 and 348 are normally held in the relative positions shown in Figs. 36 and 37^a by springs 379 380, respectively. Each of the valve-rings 450^f to 450^j is provided with a recess 468, divided by a pin 469. Normally the catches 378 lie in the lower part of the recess, as shown in Fig. 36. The under side of the pins and the head of each catch are curved, so that when one of the valve-rings is shifted by its arm 328 the catches are pushed back by the pin, but under the tension of the spring 380 fly back into the recesses 468, and the catch corresponding to the shifted ring being now in the upper portion of the recess holds the said ring from returning to normal position.

If now one of the valve-rings 450^a to 450^e be shifted by the depression of its arm 327, the nose 340 presses down and passes beneath the common bar 341. This movement has no action on the catches, the arms 345 being simply lifted away from the bar 346 and returning again to their normal position. When, however, the arm 327 is raised as the valve-ring returns to its normal position, the nose 340 lifts the common bar 341, and the arms 345 depressing the bar 346 the catches 378 are withdrawn from the recesses 468 and any shifted ring held by one of the catches returns to normal. Before the arm 327 reaches its normal or horizontal positions its nose releases the bar 341 and the parts return to the position shown in Fig. 36.

From an examination of the diagram Fig. 40 it is seen that most of the bars marked "Upper section," "Lower section," and "Middle section" correspond to similar characters in each 5 section. These corresponding bars in each section engage with arms 329, fixed on the same rocking shaft or shafts, and operate the same valve ring or rings, there being only one port in the valve for each character.

10 It is evident that instead of a series of valve rings or disks, as herein described, a series of oblong plates may be employed adapted to be shifted endwise by the arms 327 and 328.

15 The valve-port pipes 453 are carried in the box 11 to the lino-machine keyboard. Any suitable device may be employed to enable the puff of air sent through one of these pipes to depress a lino-key whenever the valve-rings are shifted to open a port. A convenient 20 device is a loosely-fitting piston 470^a, working in the end of each pipe 453, the end of the piston resting on its corresponding lino-key. An opening 471 allows the air to escape when the piston is lowered. The spring 25 of the lino-key returns the piston.

30 In the foregoing description I have shown how at each simultaneous depression of two or more finger-pieces on the keyboard permutation-bars corresponding to those keys are placed in operative position and held in such position during one revolution of the assembling-drum. I have also shown how as each bar is lifted successively a port in a valve 35 is opened and a current of air caused to operate a key of the linotype-machine.

35 I have stated that the permutation-bars are lifted by the selecting-stud arms, these latter being raised by studs on the assembling-drum. If, therefore, these studs were placed 40 spirally around the drum, it is evident that such permutation-bars as were in operative position would be successively raised and a record obtained corresponding to the position of the bars as they stand in the machine. As 45 regards the permutation-bars corresponding to the middle section of the board, this is what happens, only one stud being provided on the assembling-drum for each bar. The selecting stud arms 364 to 369, which operate 50 these bars, are provided with fixed noses or distance-pieces 381, these latter being of such a height as to be in contact with the bottom of the permutation-bar when the arm is resting on the surface of the assembling-drum. 55 One of these permutation-bars 313, corresponding to the consonant "j," is shown with its selecting-stud arm 364 in Fig. 35, in full lines showing the inoperative position, in dotted lines showing the operative position, and 60 in chain lines showing the lifted position. By looking at the diagram Fig. 38 it will be seen that the port corresponding to the letter "j" requires the valve-rings 450^a and 450^c to be shifted. The permutation-bar consequently 65 engages two arms 329, so that when lifted it rocks the two shafts 330 and 332, the arms 327 of which shafts shift those valve-

rings. To carry out this invention, however, it is necessary to be able to vary the order in which the permutation-bars corresponding to the top and bottom sections of the board are lifted, and for this purpose more than one stud on the assembling-drum is provided capable of engaging each selecting-stud arm; but only one of these must affect 70 the permutation-bar during a single revolution of the drum, so that the selecting-stud arms must only act on the permutation-bars during a portion of each revolution. This might be effected by making the selecting- 75 stud arms to normally rest between the selecting-studs and moving them sidewise to engage the studs and the permutation-bars at the desired moment in each revolution. I prefer, however, to effect this object by making the noses or distance-pieces on the arms 80 adjustable vertically and providing mechanism to place them in and out of operative position, as required.

85 *Selecting-stud arms—Adjustable distance-pieces.*—The arrangement of these adjustable distance-pieces is shown in plan in Fig. 24 and in side view in Figs. 28, 29, and 30. Each 90 of these distance-pieces consists of an oblong plate 382, pivoted onto one side of the free 95 end of the selecting-stud arm by a pin 383 and provided with a hooked offset 384, forming a slot with the body of the plate, and in this slot a rod 385 is engaged which serves 100 to place and hold the distance-piece in position. The distance-piece is shown in inoperative position in Fig. 28 and in operative position in Figs. 29 and 30. The different mechanisms affecting their position will now be described.

105 It will be remembered that the mechanisms of the top and bottom sections of the keyboard were identical in arrangement. So, too, the mechanisms affecting the distance-pieces of the stud-arms corresponding to those sections are identical, and the description of one 110 will apply to both. The distance-pieces of the stud-arms 353, allotted to the permutation-bars representing vowels in the upper 115 section, are all operated simultaneously, their rod 385 being common to all. It will be remembered that the rod 385 is engaged in a slot in the body of each distance-piece, so that when one distance-piece is raised by its 120 arm passing over a selecting-stud the rod moves up in the slots of the other distance-pieces with which it is engaged and does not alter their position. This is important, since 125 only one distance-piece is raised at a time. This rod 385 is carried on two arms 386, which have another rod 387 pivotally hung on arms 130 388 of a sleeve 389, the sleeve being movably carried on a shaft 390, fixed in the standards 6 and 7. The rod 387 is held in contact by spiral springs 391 (which may be conveniently fastened on the arms 388 and a rod held in the standards 6 and 7) with a cam 392, movably carried on a shaft 393, fixed in the standards 6 and 7. The cam is shaped as shown in Figs. 135

28 and 29 and is operated by a ratchet-wheel 394, the pitch of whose teeth is such that movement of the wheel the distance of one tooth places the rod 387 alternately on the lowest point of the cam-surface, as shown in Fig. 28, (when the distance-pieces are inoperative,) and on the highest, as shown in Fig. 29, (when the distance-pieces are in operative position.) The ratchet-wheel is actuated by a spring-pressed pawl 395, carried on the curved end of an arm 396, depending from a sleeve 397, movably carried on a shaft 398, fixed in the standards 6 and 7. It is evident that whenever the arm 396 is swung forward the cam will be shifted and any distance-pieces engaged by the rod 385 will be shifted from operative to inoperative position, or vice versa. An identical arrangement is provided for the distance-pieces corresponding to the permutation-bars allotted to consonants. There are therefore four cams and actuating mechanism—two for each section—as is seen in Fig. 24. These distance-pieces-actuating mechanisms are controlled both by special selecting-stud arms (without permutation-bars) and by the action of the reversal permutation-bar and by the permutation-bars of each section. There are two selecting-stud arms 351 and 370, which are always operative to control the distance-pieces of the top and bottom sections, respectively. Fixed on a rocking shaft 139, carried in the standards 6 and 7, Figs. 24, 26^b, and 28, are two arms 140, each with a pin 141, Figs. 24 and 28, on its free end, which engages the depending arms 396 of one of the two upper-section cams. Two similar arms which engage the depending arms of the bottom-section cams are fixed on a long sleeve 142, movably carried on said rocking shaft 139. The selecting-stud arm 351 (on the extreme left of the row, as shown in diagram Fig. 40 and Fig. 24) has a vertical arm 143, Fig. 26^b, the free end of which is connected by a long link 144 to an arm 145, fixed on the rocking shaft 139. Consequently whenever the lug of the selecting-stud arm 351 passes over a stud on the assembling-drum the shaft 139 will be rocked and the position of the upper-section distance-pieces changed. The selecting-stud arm 370 (on the right of the row of arms) is similarly connected to the rocking sleeve 142, Fig. 24, and in like manner shifts the lower-section distance-pieces.

55 *Reversal.*—It will be remembered that a pedal is provided with the keyboard to reverse the normal order of the record (from left to right) when two keys are struck in one section or the normal order of sections (top first, bottom second) when a key is struck in each section. The function of the reversal permutation-bar 319, put in operative position by this pedal, is to act on the distance-pieces, and its arrangement is shown in Figs. 24, 31, 32, 33, and 34.

Referring first to Figs. 24, 31, and 32, the reversal selecting-stud arm 372 is provided

with a fixed nose or distance-piece 381, like those of the middle section. The permutation-bar 319 has no effect on and does not operate a valve-ring. It is provided near its lower end with a pin 399, extending on both sides to engage two bent arms 146, carried on collars 147 on the shaft 374, one on each side of the stud-arm 372. Each collar has a vertical arm 148, connected by links 149—the arm on the right hand of the permutation-bar to an arm 150, fixed on the rocking shaft 139, the one on the left hand to an arm 151, fixed on the rocking sleeve 142. Consequently whenever the reversal permutation-bar is in operative position and its stud-arm lug passes over a selecting-stud the distance-pieces of both the top and bottom sections will be shifted.

When the order of sections is to be reversed, it is necessary to provide an extra shift for the distance-pieces of the lower section. This must only operate when a chord is struck comprising a key on both the top and bottom sections and the reversal-pedal. The special mechanism for this purpose is shown in Figs. 24, 32, 33, and 34. The selecting-stud arm 371 has no permutation-bar, and therefore no nose or distance-piece, but is provided with a pin 152. Carried on the shaft 374 on the right hand of the stud-arm 371 is a collar having a horizontal arm 153 and a vertical arm 154. The vertical arm 154 is connected by a link 155 with the arm 151, already described as fixed on the rocking sleeve 142. Secured to the horizontal arm 153, so as to be capable of endwise movement by two pins 156, engaged in a slot 157, is a plate 158. The plate 158 has two vertical offsets 159 and 160 and a third taller offset 161, which engages the pin 399 of the reversal permutation-bar when the latter is in the inoperative position, as shown in Fig. 33. The offset 160 engages a pin on the free end of an arm 162, fixed onto a rocking shaft 163, carried in the standards 6 and 7. Fixed on the rocking shaft, one on each side of the vowel permutation-bars of the upper section, are two arms 164, carrying a rod 165, held in contact with the edges of these permutation-bars by a spring 166. The arms 162 and 164 are so placed relatively to each other that the offset 160 engages the pin on the arm 162 when the vowel permutation-bars are in inoperative position, as seen in Fig. 33. The offset 159 is similarly engaged by a pin on an arm 167, fixed onto a rocking sleeve 168, carried on the shaft 163. The rocking sleeve has arms 169, carrying a rod 170, held by a spring 171 in contact with the vowel permutation-bars of the bottom section. The springs 166 and 171 are shown broken off in Fig. 32 for the sake of clearness. The plate 158 is provided with a recess 172 to receive the pin 152 of the selecting-stud 371. A nose 173 projects half-way across this recess. A spring 174, one end of which is fastened to the plate 158, and the other to the stud-arm 371, tends to pull the

- plate forward against the pins engaged with the offsets 159, 160, and 161. When the reversal permutation-bar and all the vowel-bars of both sections are in inoperative position, 5 the three offsets 159, 160, and 161 are held by their respective pins, as shown in Fig. 33, and the pin 152 of the stud-arm 371 plays up and down in the recess 172 when the stud-arm lug passes over a stud of the assembling-drum. 10 Moreover, if any two of the offsets be freed, the third offset being engaged, the plate 158 is still held in its backward position. If, however, a vowel permutation-bar in each section and the reversal permutation-bar are 15 simultaneously placed in operative position, the three offsets are all released and the plate pulled forward by the spring 174 into the position shown in Fig. 34, its nose 173 engaging the pin 152 of the stud-arm 371. 20 When now the stud-arm passes over a selecting-stud, the plate and the horizontal arm 153, to which it is attached, are raised along with the stud-arm, the vertical arm 154 is thrown back, and the sleeve 142 thereby 25 rocked, shifting the distance-pieces of the bottom section. When the reversal permutation-bar is returned to inoperative position, its pin 139 engaging the offset 161 returns the plate to the position shown in Fig. 33, releasing 30 the pin of the selecting-stud arm 371.

Permutation-bar cut-out.—In the cases above described the shifting of the distance-pieces is controlled by studs on the assembling-drum. When, however, two syllabic keys, both of which are in the same section of the board, are struck as a chord, it is necessary to provide for a further shifting of the distance-pieces, which will only take place when such a chord is struck. When two syllabic keys are struck in one section, it will be remembered that two bars allotted to vowels and two bars allotted to consonants are placed in operative position, and the second vowel-recording permutation-bar is utilized to shift the distance-pieces of the vowel-bars and the second consonant-bar those allotted to the consonants. There are therefore four similar mechanisms, one for each vowel and one for each consonant group of permutation-bars in each section. The arrangement will be described in connection with Figs. 28, 29, and 30, which are vertical sections on the line XXVIII XXVIII of Figs. 24, 25, and 26, showing the vowel permutation-bars of the upper section (with the exception of the bar allotted to "u") and their distance-pieces-operating mechanism in three positions. Each bar is provided with a hook 175 and with a nose 176, having an inclined upper edge.

It will be remembered that the curved arm 396, carrying the operating-pawl of the distance-piece cam, depends centrally from a rocking sleeve 397, carried on a shaft 398. 65 On each end of this sleeve is a horizontal arm 177, on the free ends of which is fixed a bar 178. A short distance in front of the bar 178

is a second bar 179, carried on two arms 180, fixed on collars 181, revolvably carried on the shaft 398, one on each side of the sleeve 397. 70 Each collar 181 has a vertical arm 182, and on each arm is a horizontal catch 183. The free ends of the arms 182 carry a spindle 184, on which are pivoted two arms 186, the free ends of which are joined by a bar 185, (hereinafter called the "cut-out" bar,) having a sharp upper edge. The arms 186 rest on a bar 187, and immediately in front of this bar each arm has a steep cam curve formed on a lug 188. Below and slightly behind the 80 catches 183 is a horizontal bar 189, so placed as to engage the catches if these be tilted slightly backward. The arms 182 are normally held by springs 299^a against a stop-bar 299, common to all these sections, secured on the 85 standards 6 and 7. The operation is as follows: In Fig. 28 all the parts are shown in inoperative position. In Fig. 29 the distance-pieces and two of the permutation-bars—say those corresponding to "a" and "e"—have 90 been placed in operative position, the end of the noses 176 of these bars being now under the bar 179. The selecting-stud arm corresponding to the bar "a" is the first to engage with a selecting-stud, and that bar is raised 95 into the position shown in Fig. 30. In rising its nose, lifting the bar 179, tilts the vertical arms 182, pulling back and at the same time raising (by means of the cam-lug 188) the bar 185, which engages with the hook 175 of the 100 permutation-bar "e" and pulls it forward into the position shown in Fig. 30, so that its point is clear of its distance-piece. By being pulled forward the inclined edge of its nose 176, engaging with the bar 178, tilts the arms 105 177 and operates the distance-piece cam, which is shown in the position in which the rod 387, engaging it, is about to fall back and place the distance-pieces into inoperative position, allowing the raised permutation-bar 110 to fall to normal operative position. It will be seen that the catch 183 has engaged the bar 189. The cut-out permutation-bar will therefore remain cut out until the catch is released. This is done by the action of special assembling-drum studs on the stud-arms 350 and 350^a, as shown in Figs. 24, 26, and 26^a. The bar 189 is pinned at each end to a short arm 190, carried on a sleeve 191, rocking on a pin 192, fixed one in each standard 120 6 and 7. Each stud-arm 350 350^a engages a pin 193 on one end of a lever 194, pivoted on a pin 195, (in the standards 6 and 7, respectively,) the other end of the lever being connected by a vertical link 196 to the 125 bar 189. The bar 189 is common to all the cut-out mechanisms, and the two stud-arms 350 350^a act in unison. When these are raised by their studs, the bar 189 is lowered and the catch 183 released. The arrangement of this 130 permutation-bar cut-out mechanism for shifting the distance-pieces is the same for the group of consonant-bars as for the vowel-bars, with one exception. The bar 187 for the

vowel group of each section is capable of movement, being carried on one arm of a bell-crank lever 197, pivotally carried on a bracket 198, depending from the cross-piece 5 of the frame, as shown in Figs. 26 and 27. The bar 187 for the consonant groups is fixed on brackets 199 and is incapable of movement. The reason for making the vowel-bar movable is to give effect to the automatic 10 vowel-control mechanism.

It will be remembered that two mechanisms were described, one for the top and one for the bottom section of the board, to automatically insure that the normal record of 15 the vowels of two syllabic keys should be from left to right and that these mechanisms each placed a record-stud in operative position. These record-studs place the permutation-bars 301 and 312 in operative position, 20 and they are attached, as seen by the diagram Fig. 40, to the top and bottom sections, respectively. Placed next to the bars 301 and 312 are two bars numbered 301^a and 312^a, respectively. The arrangement for both sections is identical, and I will describe that belonging to the top section. (Shown in side elevation in Fig. 27.)

The permutation-bars 301 and 301^a are shown detached in Figs. 27^b and 27^c. The 30 bar 301 has no offset 340, as it does not operate a valve-ring, but is provided with a horizontal arm 470 on its back edge and a lug 471 on its front edge. The lug carries a pin 472, which engages the back of the permutation-bar 301^a and brings it into operative position when the bar 301 is so placed. The only function of the bar 301^a is to shift the valve-ring 450ⁱ. It is a plain bar with an offset 340, which engages an arm 329 on the rocking 35 shaft 339. When in inoperative position, the back edge of the permutation-bar is in engagement with an arm of the bell-crank lever 197, the other arm of which carries the bar 187, as above described, as shown in Fig. 40. 40 The bell-crank lever is held in contact with the permutation-bar by a spring 200, one end of which is fastened to one arm 197 of the bell-crank, while the other may be fastened to the rocking shaft 333. Consequently 45 when the permutation-bar is brought into operative position the bar 187 is lowered by the action of the bell-crank 197, and the arm 186 being no longer supported by the bar swings down into the position shown in Fig. 27^a. 50 If now, as shown in Figs. 29 and 30, two vowel permutation-bars are in operative position and one of them raised by its stud-arm, although its nose 176 engages the bar 179 and tilts the arm 182, owing to the altered position of the bar 185, this will not engage the catch 175 of the unraised permutation-bar. The latter consequently will not be cut out nor will the distance-pieces be shifted by it. When the permutation-bar 55 60 65 301, however, is raised, the distance-pieces are shifted by its arm 470 engaging a pin 473, carried on a depending lug 474 on one of

the arms 177, which, it will be remembered, form part of the sleeve carrying the curved cam-operating arm 396. The permutation-bars 301 and 301^a are raised by selecting-stud arms 352 and 352^a, respectively. The bars 312 and 312^a of the bottom section are raised by stud-arms 363 and 363^a. These stud-arms have movable distance-pieces operated by 75 70 75 the rod 385 common to the distance-pieces of their respective groups of bars. The manner in which this mechanism affects the record will be understood when the operation of the apparatus is described.

Repeat-bars.—It will be remembered that the repeat shift-keys 46 and 46^a of the top and bottom keyboard-sections, respectively, each control two bellows and so place two record-studs in position. These record-studs 85 each control a permutation-bar placed one in each vowel group and one in each consonant group of bars in both top and bottom sections. These bars are numbered 302^x, 305^x, 308^x, and 311^x, Fig. 40. They have no selecting-stud arms allotted to them and are therefore made shorter than the other bars and have no offset 340. Otherwise they resemble the character permutation-bars of the top and bottom sections. One such bar 302^x 95 is shown in Fig. 29. Their function is to operate the permutation-bars cut-out mechanism when only one character-bar of a group is placed in operative position and a repetition of its record is desired.

Shift-bars.—The permutation-bars allotted to the shift-keys 35, 35^a, 43, 43^a, and 35^b are numbered 303, 307, 306, 309, and 314, respectively, and each engages an arm 329 on the rocking shaft 335, whose arm 328 shifts the valve-ring 450^f. The bars allotted to the shift-keys 36, 36^a, and 36^b are numbered 304, 310, and 315, respectively, and each rocks the shaft 336, whose arm 328 shifts the valve-ring 450^g. These shift permutation-bars are 100 105 110 like the character-bars of the middle section, having no hooks or arms, their only function being to shift a valve-ring. They are raised by stud-arms having distance-pieces similar to those of the section to which they are allotted, those corresponding to the bars 314 and 315 being fixed and the other adjustable. The permutation-bar allotted to the space-key is numbered 316. It rocks the shafts 331 and 333, shifting the valve-rings 450^b and 450^d. The bar allotted to the "caps" shift-key is numbered 318 and that to the "numerals and stops" shift-key 317. They shift the valve-rings 450^h and 450ⁱ, respectively. These three bars are like those of the middle 115 120 125 section. They have no hooks or arms and are operated by selecting-stud arms having fixed noses or distance-pieces.

The selecting mechanism.—The assembling-drum 400, which forms the selecting mechanism, is a hollow cylinder carried by arms on central bosses keyed onto a shaft 426, running in bearings 427 on the standards 6 and 7. It is constantly revolved while the apparatus

is working and may be driven from any convenient source of power—say by a belt and pulley 475. On the surface of the cylinder are a number of curved studs, which we call 5 “selecting-studs,” adapted to engage as the drum revolves with the lugs 375 of the selecting-stud arms before described. The arrangement of these selecting-studs is shown diagrammatically in Fig. 39, which represents 10 the surface of the assembling-drum 400 spread out flat. The letters represent studs which operate permutation-bars to shift valve-rings to record characters, the crossed studs which operate bars allotted to the shift-keys and 15 space-key and which bars also shift valve-rings. The “O” represents studs which only affect the position of the distance-pieces, the “—” the studs which operate the stud-arms which release the permutation-bars cut out, 20 and the “*” the two studs which control the position of the record-drum latches. The diagram is divided into columns. All the studs in each column have the same function and are identified by the numbers 401 to 425, 25 placed at the head of the same. The diagram is also divided into compartments numbered O to VII^A. The arrow by the side of the diagram shows the direction of movement of the drum. It is of course clearly understood that 30 all the studs are identical in shape, and they all operate by rocking selecting-stud arms. The letters and signs by which they are marked, as also the lines indicating the columns and compartments, are purely imaginary and placed on the diagram merely for 35 clearness of description. The stud-arms and permutation-bar corresponding to each column of selecting-studs are shown in diagram 40. The studs 403 to 408 correspond to the 40 top-section devices, and a complete set of studs to operate all the bars of that section are placed in the compartments I, III, and VI, similarly a complete set of studs 409 to 414 corresponding to the bottom section in 45 compartments II, IV, and V. In each case it will be noticed that the character-studs are placed in reverse order in compartments III and IV to those in compartments I, II, V, and VI, the character which is at the bottom of the 50 compartment in the latter being placed at the top in the former. Consequently if two permutation-bars are in operative position in either of the columns 404, 407, 410, or 413 the one which would be operated first (in one revolution of the drum) by the studs in compartments I, II, and VI would be operated last in compartments III and IV. The studs 413 to 55 415, corresponding to character permutation-bars of the middle section, are placed in compartment VII, coming last in each revolution of the drum, with the single exception of the stud 418, corresponding to the space-key, which is placed last of all in compartment VII^A. The studs 419 and 420, corresponding 60 to numerals and stops, are placed at the top of compartment I. The record-drum-latchet-operating stud 425 marks the beginning of

each revolution of the assembling-drum and is placed at the top of compartment O. The studs 401 and 424, which operate the permutation-bar cut-out release, are placed on the bottom of each compartment. Since these studs merely operate to lower the bar 189 and release the catch of the cut-out device, it is obvious that when the cut-out mechanism is not in action these studs have no effect on the operation of the apparatus, although the mechanism controlled by them is constantly actuated. The studs 402 and 421, which operate to shift the distance-pieces of the top and bottom sections, respectively, have each a stud in compartment O and a second stud 402 in compartment II^A and 421 in compartment III^A. There are also two each of the reversal studs 422 and 423. 70 75 80 85

It must be remembered that the studs 401, 402, 421, 424, 425, and 425^A are always in operative connection with the devices they control, that the studs 415 to 420 and stud 423 affect the record when a permutation-bar is 90 in operative position only, that the studs 403 to 414 only affect the record when one or more permutation-bars and their stud-arm distance-pieces are in operative position, while the stud 422 requires both the reversal permutation-bar and a bar in both the top and the bottom section to be all three in operative position for any action to result. 95

Operation.—In order that the action of the apparatus may be more readily understood, 100 I will now give concrete examples of the various records obtainable by the operation of one key or by the simultaneous operation of two or more keys of the keyboard.

In the foregoing description I have shown 105 how by the depression of one key or of a chord of keys one or more record-studs are placed in operative position in one row on the record-drum, that at each revolution of the assembling-drum the studs thus placed push 110 corresponding permutation-bars into vertical or operative position over and in engagement with distance-pieces on the free ends of the selecting-stud arms, that these stud-arms are rocked by the selecting-studs on the revolving assembling-drum and when rocked successively lift the operatively-placed permutation-bars, and that each of the latter when lifted acts on a multiported valve to operate 115 a selected key on the linotype-keyboard. It 120 must be remembered that the valve-ports are opened by the permutation-bars when lifted, shifting one or more of ten disks 450^A to 450^B, and that while five of the disks 450^A to 450^C return to normal position directly the lifted 125 permutation-bar falls, the other five, 450^D to 450^J, remain shifted until one of the five disks 450^A to 450^E has been shifted and returned to normal. The mechanism is so arranged that the movable distance-pieces of both top and 130 bottom section are always out of operative position at the end of each complete revolution of the assembling-drum. The assembling-drum moving in the direction of the ar- 135

row, Fig. 39, the first stud to rock a stud-arm is the stud 425, (compartment O.) This controls the moving mechanism of the record-drum latches to put them in line with a fresh row of record-studs. If no key or keys have been struck, and therefore no record-studs placed in operative position, no record is made during that revolution; but the distance-piece-shifting studs 402 and 421 in compartment O put in the distance-pieces for the top and bottom sections of the board, respectively, and similar studs in compartments II^a and III^a again put them out.

One syllabic key—Top section of board—
15 Say to obtain record “at:” The “a” key in the fourth column of the upper section 12 of the keyboard is depressed. The permutation-bars 302 “a” and 305 “t” are placed in operative position. The distance-stud 402, compartment O, puts in the distance-pieces of the top section. Studs 404 “a” and 407 “t” in compartment I successively lift the two permutation-bars. The bar 302 “a” rocks the shaft 331 and shifts the valve-ring 450^b, making a free passage through the port allotted to “a,” as shown in Fig. 38, operating the Lino key allotted to that character. The valve-ring returns again to normal and closes the port directly the stud-arm is free of its 30 selecting-stud. The bar 305 “t” next rocks the shafts 330, 331, and 333, shifting simultaneously the valve-rings 450^a, 450^b, and 450^d, making a free passage through the port allotted to “t,” Fig. 38. Stud 402, compartment II^a, puts out the distance-pieces of the section, and the studs 404 “a” and 407 “t” in compartments III and VI are consequently inoperative.

One syllabic key—Top section, second consonant—Say “ap:” The same syllabic key is depressed as before, but as a chord, along with either of the shift-keys 35. The same permutation-bars 302 “a” and 305 “t” and the permutation-bar 303 are put in operative position. The stud 402, compartment O, puts in the distance-pieces of the top section. Stud 404^a, compartment I, lifts bar 302 “a” and opens the “a” port of the valve and directly closes the same, as in first example given. Stud 405, compartment I, lifts the bar 303, which rocks shaft 355, shifting the valve-ring 450^c. (It will be remembered that the rings 450^e to 450^f remain shifted until after one of the valve-rings 450^a to 450^c has been shifted.) Stud 407^t lifts the bar 305 “t,” which rocks shafts 330, 331, and 333, shifting the valve-rings 450^a, 450^b, and 450^d. The four valve-rings 450^a, 450^b, 450^d, and 450^f are therefore now in the shifted position, and the fourth 60 port of those allotted to the second row of consonants, Fig. 38, has a free passage through it operating the lino-key allotted to the character “p.” The stud 402, compartment II^a, shifts the distance-pieces of the top section 65 to inoperative position, and the studs in compartments III and VI are inoperative.

One syllabic key—Top section, third con-

sonant—Say “ab:” The action is like that last described; but either one of the shift-keys 36 is struck instead of 35. Permutation-bar 304 is placed in operative position in place of 303, and disk 450^e is shifted instead of 450^f.

One syllabic key—Bottom section—Say “ta,” “pa,” or “ba:” The actions are similar to those above described for the top section, the “a” key of the bottom section in the fourth column being struck and the shift-keys 35^a and 36^a to obtain the second and third consonants, respectively. The corresponding permutation-bars 308 and 311 (and 80 when the shift-keys are struck the bar 307 and 310) are placed in operative position, and the studs in compartment II are utilized. As shown in Fig. 38, in this compartment the consonant-studs 410 come before the vowel-studs 413, the reverse of the order in compartment I. Consequently, although the same valve-rings are shifted by the permutation-bars 302 and 305, as by the bars 311 and 308, respectively, in the one case the 85 valve-ring affecting the vowel-port is first shifted and in the other that opening a consonant-port.

Two syllabic keys—Top section of board, struck as a chord. Normal order—Say 95 “emul:” The “e” key in the fifth column and the “u” key in the eighth column are depressed simultaneously. The permutation-bars 302 “e,” 302 “u,” 305 “m,” and 305 “l” are placed in operative position. Stud 402, compartment 100 O, puts in the top-section distance-pieces, and the studs, compartment I, lift the permutation-bars. As shown in Fig. 39, as the drum revolves the “e” stud 404 comes before the “u” stud. The permutation-bar 302 “e” is 105 therefore lifted, rocks the shaft 330, and shifts the valve-ring 450^a, giving a free passage through the port “e.” At the same time its nose 176 engaging and raising the bar 179 Figs. 28, 29, and 30 causes the bar 185 to 110 catch the hook 175 of the vowel permutation-bar “u” and draws the latter backward out of operative position, so that it is not lifted by the stud “u” in compartment I. The inclined portion of the nose of the latter bar 115 now engages and lifts the bar 178, operating the cam 392 and putting out the distance-pieces of the vowel-section. The two consonant-bars act in a similar manner. The stud 407 “m” lifts the permutation-bar 305 “m,” 120 which rocks the shafts 331 and 332 and shifts the valve-rings 450^b and 450^c, opening the port “m” and at the same time cuts out the permutation-bars 305 “l” and puts out the consonant distance-pieces. The studs 401 125 and 424, compartment I^a, restores the vowel cut-out, and stud 402, compartment II^a, puts in the distance-pieces again for both vowel and consonant bars. The record of the characters “e” and “m” have therefore now been 130 obtained. The studs in compartment III now act like those in compartment I; but the order of the studs being reversed the “u” and “l” permutation-bars are operative and the

"e" and "m" bars cut out, and the record is completed by obtaining the other two characters "u" and "l." There being no stud 402 in the remaining compartments the distance-pieces put out by the permutation-bar cut-out remain out and the studs in compartment VI do not operate.

Two syllabic keys—Top section of board—Second and third sets of consonants: The shift-keys 35 and 36, respectively, are struck as part of the chord, controlling permutation-bars 303 and 304, lifted by studs 405 and 406, respectively. The operation is the same as when the shift-key is struck with a single syllabic key; but as will be readily understood from the position of the studs 405 and 406, as shown in Fig. 39, these only affect the first consonant of the chord. The shift-key 43 is struck when the second consonant is desired with the second syllabic key of the chord. This operates permutation-bar 306, lifted by stud 408.

Two syllabic keys—Bottom section of board—Say "he ro:" The mode of operation is the same as for the top section, permutation-bars 308 and 311 being lifted by studs 410 and 413 in compartments II and IV. As is seen in Fig. 39, the consonant-studs in these compartments precede the vowel, and therefore the record is obtained with the consonant of each syllabic preceding the vowel. Shift-keys 35^a and 36^a are struck to obtain the second set of consonants, and shift-key 46^a the third set, studs 409, 412, and 411 operating respectively.

Two syllabic keys—In either the top or the bottom section—Normal order reversed—Say "aler" or "nice:" As before stated, and as will be readily understood from the arrangement of the studs, as shown in the diagram Fig. 39, when a chord of keys is struck in one section the record called for by the syllabic key to the left hand of the board is obtained first. It is obviously desirable that the operator should be able to reverse this order at will. For this purpose the reversal permutation-bar 319 is provided, controlled as to operative position by the foot-pedal and operated by studs 423. The only action of this bar, it will be remembered, is to change the position of the distance-pieces. For example, if the "e" key in the sixth column and the "a" in the eighth column of the top section are struck as a chord the normal record obtained is "eral." If it is desired to obtain the record "aler," these keys are struck simultaneously with the depression of the pedal. The permutation-bars 302 "e", 302^a, 305^a, 305^l, and the reversal bar 319 are placed in operative position. Studs 402 and 421, compartment O, as usual, put in the distance-pieces for the top and bottom sections, respectively, and stud 423 in the same compartment, acting through the reversal bar, immediately puts them out. Compartment I is consequently inoperative. Stud 402, compartment II^a, again puts them in and compartment III is opera-

tive. In this compartment the studs act from right to left and the permutation-bars 302^a and 305^l are lifted and shift their corresponding valve-rings. The bars 302^a and 305^l are cut out (as in the normal action of a syllabic chord) and put out the distance-pieces. The studs 401 and 424, compartment III^a, restore the cut-out, and stud 423, compartment IV^a, puts in the top-section distance-pieces. Compartment VI operates to give the second syllable of the record-lifting permutation-bars 302^a and 305^l. The bars 302^a and 305^l are cut out and the distance-pieces put out. Studs 401 and 424, compartment VI^a, restore the cut-out. If a bottom-section record is desired, the studs in compartments IV and V and the corresponding permutation-bars allotted to that section operate.

Repeating the same vowel or the same consonant, or both, in a chord of two syllabic keys in either top or bottom section—Say "alan," "here," "lila," "anan," "mama:" It will be remembered that in the description of the keys of the board and of the mechanism operated thereby all the syllabic keys in one row put the same record-drum stud into operative position to give the vowel-record; also, that the same record-drum stud, giving a consonant-record, is placed in operative position by the action of any one of the five keys in a vertical column in either section of the board. It will also be remembered that when two vowel permutation-bars or two consonant permutation-bars in one section are in operative position at the same time the lifting of one bar causes the other to alter the position of the distance-pieces of that section. Consequently if two syllabic keys in the same row be struck as a chord only one vowel permutation-bar is placed in operative position, and if two syllabic keys in the same column only one consonant permutation-bar, and in either case the distances-pieces not being acted on a false record would be obtained. It is to meet these cases that the repeat permutation-bars 302^x, 305^x, 308^x, and 311^x are provided in addition to the normal vowel and consonant bars of the top and bottom sections, respectively. These bars, Fig. 28, have no selecting-stud levers and do not shift the valve-rings, their only function being to shift the distance-pieces of their respective sections through the permutation-bars cut-out mechanism. These repeat-bars are placed in operative position in the top and bottom sections by the repeat shift-keys 46 and 46^a, respectively. To obtain, for instance, such a record as "alan," the operator strikes the "a" keys in the eighth and tenth columns of the top section along with the repeat shift-key 46 as a chord. The action is identical with that which takes place when a normal chord is struck, the repeat permutation-bar 302^x shifting the distance-pieces, and the same permutation-bar 302^a is lifted in both compartments. If it is desired to repeat both letters of the syllable, the

proper syllabic key is depressed along with the shift-key. For example, to obtain such a record as "mama," the "a" key in the fifth column of the bottom section is struck 5 along with the repeat shift-key 46^a.

Automatic control of order of vowels: It will be remembered that in describing the keyboard an automatic mechanism was described, the object of which was to cause the 10 vowel record to be always given from left to right, and that among the recording mechanisms two permutation-bars in each of the top and bottom sections, numbered 301 and 301^a, 312 and 312^a, respectively, were allotted for 15 this purpose. Say, for instance, that the record "hose" is desired. The operator strikes the "o" key in the second column and the "e" key in the third column of the bottom section. Were no automatic mechanism 20 provided the record obtained would be "he so," as will be readily understood from the arrangement of the studs in compartment II of Fig. 39. The automatic mechanism, however, puts the permutation-bar 312 into 25 operative position, and this, by means of its pin 472, puts the bar 312^a as well into operative position, and also by means of the bell-crank lever 197 lowers the bar 187 and renders the permutation-bar cut-out inoperative. 30 (Figs. 27 and 27^a may be referred to. They illustrate the top-section bars; but everything is identical except the number designating the bar.) Stud 421, compartment O, 35 puts in distance-pieces of bottom section. The consonant-bar 308^b, compartment II, is lifted and the valve-rings 450^a, 450^b, and 450^c 40 shifted and returned to normal. The permutation-bar cut-out cuts out bar 308^b and puts out the consonant distance-pieces. Stud 414^a, compartment II, lifts the bar 312^a, which, rocking the shaft 339, shifts the valve-ring 450ⁱ and closes the valve-ports e, a, i, o, and u. This ring is, it will be remembered, held in the 45 shifted position by catch 378, Fig. 36. Stud 413^c, compartment II, lifts the permutation-bar 311^c and shifts the valve-ring 450^a, which would normally open the port e, but this has been closed by the ring 450ⁱ and no action ensues. The return to normal of the ring 50 450^a releases the catch and valve-ring 450ⁱ likewise returns to normal. The permutation cut-out being inoperative, the stud 413 "o" in the same compartment II lifts the bar 311 "o" and gives the desired record. 55 Stud 414 in compartment II^a lifts the permutation-bar 312 and puts out the distance-pieces, (its nose 470 engaging the pin 473.) Stud 421, compartment III^a, puts in the bottom-section distance-pieces, and compartment 60 IV operates in a similar manner to compartment II to give the record of the second consonant and vowel. The top section operates in a similar manner the bars 301 and 301^a and studs 403 and 403^a, taking the place 65 of 312 and 312^a and 414 and 414^a, respectively. It must be remembered that this action is purely automatic and operates without any

control or cognizance on the part of the operator.

One syllabic key in each section—Normal 70 order—Say "alto": Two syllabic keys, one in each section, struck as a chord. One each of the permutation-bars 302, 305, 308, and 311 are placed in operative position, and the studs in compartments I and II operate successively. The studs 402 and 421 in compartments II^A and III^A, respectively, put out the distance-pieces, and the following compartments are inoperative, as in the case when a single syllabic key is struck in either section. 80

Reversal of normal order of board-sections, say "foam:" Normally when a chord of two syllabic keys is struck, one key being in each section of the board, the characters called for by the key of the top section appear first in 85 the record—that is, the syllable beginning with a vowel precedes the one beginning with a consonant. To obtain by a chord such words as "roam," "heat," "seat," "mite," &c., it is necessary to reverse the normal order 90 of the sections, and this is done, as far as the operator is concerned, by using the pedal, as in the reversal of order of syllabic keys in the same section, previously described. It will be remembered that the selecting stud-arm, 95 operated by studs 422, (having no bar, but arranged to shift the distance-pieces of the bottom section,) only comes into operation when the reversal bar and a bar or bars in each section are in operative position, which 100 is now the case. To obtain, say, "foam," the operator strikes the corresponding syllabic key in each section of the keyboard as a chord and simultaneously depresses the pedal. One each of the permutation-bars 302, 305, 105 308, and 311 and the reversal-bar 319 are placed in operative position. As in every case the studs 402 and 421, compartment O, put in the distance-pieces of the top and bottom sections, respectively, the reversal-stud, compartment O, throws out these distance-pieces, and compartment I is inoperative. Stud 422, compartment I^A, puts in the 110 distance-pieces of the bottom section, and the studs in compartment II operate. Stud 402, 115 compartment II^A, puts in the top-section distance-pieces and compartment III operates. Stud 421, compartment III^A, puts out the bottom-section distance-pieces, and compartment IV is inoperative. Reversal-stud 423, compartment IV^A, puts out the top-section distance-pieces and puts in those of the bottom section. Stud 422, compartment IV^A, puts out the bottom-section distance-pieces, and compartments V and VI are inoperative. 120 125

Single characters—Middle section of keyboard: In the foregoing operations only syllabic keys and shift-keys in the top and bottom sections of the board have been utilized. The permutation-bars controlled by the single-character keys of the middle section are operated by the studs 415 and their shift-keys to give the second and third sets of single consonants by the studs 416 and 417, respec-

tively. These studs are all placed in the compartment VII of the assembling-drum. They may be operated singly, or two or more may be struck as a chord, the record both of 5 vowels and consonants being obtained in the order from left to right, as shown on the keyboard, a vowel, however, preceding a consonant if struck as a chord with a consonant-key. One or more single keys may be struck 10 as a chord with one or with two syllabic keys; but in this case they appear in the final record after the characters called for by the syllabic keys. For instance, the word "final" 15 could be obtained at one operation by striking as a chord the "i" key, ninth column, and "a" key, tenth column, of the bottom section, along with the "l" key of the middle section, or the word "arrest" by striking as a chord the "a" key, sixth column, upper section, and the "e" key, sixth column, bottom section, along with the "s" and "t" keys of the middle section.

Capitals: The "Caps" shift-key is struck along with the desired character-key of the 25 middle section. The stud 420, compartment O, lifts the permutation-bar 318, which, as before stated, shifts the valve-ring 450^b. If the "Caps" shift-key be struck along with a syllabic key or with two syllabic or single character keys, only the first-recorded character 30 will be a capital, as will be readily understood when it is remembered that the valve-ring 450^b is returned to its normal position by the return to normal after shifting of any 35 of the five valve-rings 450^a to 450^c.

Numerals and stops: The "numerals and stops" shift-key is struck along with any character-key to which the desired numeral or stop has been assigned. They may be allotted 40 at will to any desired keys, and it is therefore not considered necessary for the purposes of this specification to specifically assign them. The stud 419, compartment O, lifts the permutation-bar 317 and shifts the 45 valve-ring 450ⁱ.

Spaces: The space-key may be struck alone or along with a key or a chord of keys. The stud 418, which lifts the permutation-bar 316 assigned to record a space, is placed after all 50 the other studs in compartment VII^a. If struck, therefore, as part of a chord with one or with more than one key, it will appear last in the record.

From the above description it is evident 55 that the operator employing both hands may by a single operation record a word consisting of five or even six characters and at will begin the word with a capital and follow it with a space. For instance, as already stated, 60 by one syllabic key in the top section, one in the bottom section, and two in the bottom section of the board shown in Fig. 5 (or one in the left hand, one in the right hand, and one in the bottom section of the board shown 65 in Fig. 6) he obtains the word "arrest." By also striking along with these keys the shift-key "Caps" and the space-key he will ob-

tain "arrest" followed by a space. Of course the ability to do this will depend on the skill of the operator; but if such a chord be considered beyond the capability of the average operator the record can be obtained in two chords, in which case only three keys would need to be struck simultaneously, which would require but a moderate amount of skill in fin- 70 gering and attention when once the keyboard has been learned.

While the apparatus hereinbefore described, in which syllabic keys and reversal and other shift mechanisms are employed, is 80 the preferred form, this invention may be carried out without the use of such devices. In Figs. 41 and 42 are shown a keyboard and a diagrammatic arrangement of the studs on the assembling-drum in which only single- 85 character keys and shift-keys for capitals and numerals and stops are employed. In this case each key controls a single air-duct, and the arrangement of permutation-bars and selecting-stud arms is similar to that for 90 the middle section of the apparatus first described, no movable distance-pieces or cut-out devices being required.

The automatic vowel-control mechanism is not required. The ring 450ⁱ of the valve is 95 therefore dispensed with, as also are the rings 450^f and 450^s, allotted to the second and third set of consonants, one character only being allotted to each key.

The board is intended to be operated by 100 both hands, and when a chord of keys is struck the record of characters obtained is, in the order of the studs as lettered on the diagram Fig. 42, from left to right, the assembling-drum 400 rotating in the direction of the 105 arrow.

In Figs. 43 and 44 is shown an arrangement whereby instead of operating the valve the shafts 330 to 339 when rocked by the permutation-bars may be caused to punch holes in 110 a paper strip, which strip may be afterward employed to control a composing-machine. Each rocking shaft is provided with an arm 515, having a punch 516 on its lower end. Each punch corresponds with a hole 517 in 115 two plates 518 519, between which the paper strip is held. The lower plate 518 is rigidly secured on the standard 6, and the plate 519 is held in contact with it by light springs 520.

The paper strip is supplied for a roll carried 120 on a pin 521 on the standard 6. It is led over a guide-wheel 536 and between the plates 518 and 519 and is fed forward each time one of the shafts 330 to 339 is rocked by the following mechanism: The free end of the 125 paper strip is engaged by two friction-wheels 522 and 523, revolvably carried on pins numbered 529 and 530, respectively, fixed on the standard 6. Below the ends of the arms 515, extending across the same, so as to be engaged by each of them, is a bar 531, carried by arms 532 533 on bosses revolvably mounted on the pin 529, one on each side of the friction-wheel 522. On the arm 532 is a spring-

pressed pawl 534, which operates a ratchet-wheel 537, rigidly connected to one end of the friction-wheel 530. A spring 535 holds the bar 531 in contact with the arms 515. 5 When now one of the shafts 330 to 339 is rocked by a permutation-bar, the arm 515 corresponding to that shaft is lowered and punches a hole in the paper band. At the same time the arm 532 is lowered, and the 10 pawl 534 engages a fresh tooth on the ratchet-wheel. On the arm 515 returning to normal position the punch is raised from the paper band, and the spring, causing the bar 531 to follow the arm, raises the arm 532 and, shifting the ratchet-wheel, operates the friction-wheels, drawing the paper band forward, so as to present a fresh surface for the next operation of a punch; but whether the multi-port valve is employed or the strip-perforating mechanism the principle of operation is the same in that there is in combination with the mechanical characters a means for controlling the transmission through a plurality of channels of power utilized in the formation 20 of a permanent record and means operated by the mechanical characters for selecting the arrangement of parts (either the ports of the valve or the perforations of the strip) that determines the channels through 25 which the power is transmitted, and therefore the characters that form the permanent record.

It is evident that any or all of the devices herein described may be readily adapted to 30 be controlled and operated electrically instead of pneumatically and that many modifications in details of construction and in arrangement may be made without departing from the spirit of this invention.

40 What I claim as my invention, and desire to secure by Letters Patent, is—

1. In a type-setting, type-writing or analogous machine, the combination with an intermittently-moving mechanism controlled by a 45 keyboard to put in operative position, at each movement, a plurality of mechanical marks each representing a character, of a constantly-revolving mechanism, which selects and operates these marks, one by one, to give a record 50 of the characters they represent in a desired sequence.

2. In a type-setting, type-writing or analogous machine, the combination with an intermittently-moving mechanism controlled by a 55 keyboard to put, at each movement, in operative position in a fixed arbitrary order, a plurality of mechanical marks each representing a character, and a constantly-revolving mechanism which selects and operates these 60 marks, one by one, to give a record of the characters they represent in a desired sequence, of mechanisms, likewise controlled by the keyboard, and operated by the selecting mechanism which determine and vary the 65 sequence in which the said marks are operated.

3. In a type-setting, type-writing or analogous

machine, and in combination, an intermittently-moving mechanism controlled by a keyboard to put in operative position at each 70 movement a plurality of mechanical marks representing characters, a constantly-revolving mechanism which selects and operates these marks one by one in a desired sequence, and means, operated by the mechanical marks 75 to make a record of the characters, substantially as specified.

4. In a type-setting, type-writing or analogous machine, and in combination; an intermittently-moving mechanism controlled by a keyboard to put, at each movement, in operative position in a fixed arbitrary order, a plurality of mechanical marks each representing a character; a constantly-revolving mechanism which selects and operates these marks 85 one by one in a desired sequence; means, likewise controlled by the keyboard and operated by the selecting mechanism, which determine and vary the sequence in which the said marks are operated; and means, operated by the mechanical marks, to make a record 90 of the characters substantially as specified.

5. In a type-setting, type-writing or analogous machine, and in combination, an intermittently-moving mechanism controlled by a keyboard to put in operative position at each movement a plurality of mechanical marks representing characters, a constantly-revolving mechanism which selects and operates 95 these marks one by one in a desired sequence, means for controlling the transmission through a plurality of channels, of power utilized in forming a record, and means operated by the mechanical characters for determining 100 the arrangement of parts which determine the channels through which such power is transmitted and therefore the characters to form the record.

6. In a type-setting, type-writing, or analogous machine, and in combination; an intermittently-moving mechanism controlled by a keyboard to put, at each movement, in operative position in a fixed arbitrary order, a plurality of mechanical marks each representing a character; a constantly-revolving mechanism which selects and operates these marks one by one in a desired sequence; means, likewise controlled by the keyboard and operated by the selecting mechanism, 110 which determine and vary the sequence in which the said marks are operated; and means such as a series of punches, operated by the mechanical marks, to make a record of the characters substantially as specified. 115

7. In a type-setting, type-writing or analogous machine and in combination; a "record-drum" having longitudinal slots in its periphery, and a series of movable studs in each slot, a series of keys, means operated by 120 the keys to shift the studs endwise in the slots, and means controlled by the keys to rotate the drum through a distance equal to 125 the distance between any two slots every 130

time a key is operated, substantially as specified.

8. In a type-setting, type-writing, or analogous machine and in combination a "record-drum" having longitudinal slots in its periphery and a series of studs in each slot, a casing, substantially as specified surrounding the drum and acting as a guide to said studs; a series of keys; means operated by the keys to shift each stud endwise in its slots; and means controlled by the keys to rotate the drum through a distance equal to the distance between any two slots every time a key is operated; substantially as specified.

9. In a type-setting, type-writing, or analogous machine and in combination, a "record-drum" having longitudinal slots in its periphery and a series of studs in each slot, a casing, substantially as specified surrounding the drum and acting as a guide to said studs; a series of keys; means operated by the keys to shift each stud endwise in its slots; means controlled by the keys to rotate the drum through a distance equal to the distance between any two slots every time a key is operated; a series of swinging latches equal in number to the studs in one slot of the "record-drum," and normally resting on the surface of the drum in the paths of such studs as have been moved endwise, so as to be swung out by the said studs when moved over them; a constantly-revolving drum, with studs fixed on its periphery; a series of swinging bars placed over said revolving drum, each bar being operatively connected with one of the aforesaid latches; means whereby, when a latchet is swung out, its corresponding bar is raised when a stud on the constantly-revolving drum passes beneath the said bar; a series of shafts, capable of being rocked by the raising of the bars; and a series of punches operated by the rock-shaft to make a record in a paper strip; substantially as specified.

10. In a type-setting, type-writing or analogous machine and in combination, a "record-drum" having longitudinal slots in its periphery and a series of studs in each slot, a casing, substantially as specified surrounding the drum and acting as a guide to said studs; a series of keys; means operated by the keys to shift each stud endwise in its slots; means controlled by the keys to rotate the drum through a distance equal to the distance between any two slots every time a key is operated; a series of swinging latches equal in number to the studs in one slot of the "record-drum" and normally resting on the surface of the drum in the paths of such studs as have been moved endwise, so as to be swung out by the said studs when moved over them; a constantly-revolving drum, with studs fixed on its periphery; a series of swinging bars placed over said revolving drum, each bar being operatively connected with one of the aforesaid latches; means whereby, when a latchet is swung out, its corresponding bar is raised when a stud on the constantly-revolv-

ing drum passes beneath the said bar; a series of shafts, capable of being rocked by the raising of the bars; and a multiported valve, each port of which corresponds to a character, the ports being opened and closed by the said rock-shafts; substantially as specified.

11. In a type-setting, type-writing, or analogous machine and in combination a "record-drum" having longitudinal slots in its periphery and a series of studs in each slot, a casing, substantially as specified surrounding the drum and acting as a guide to said studs; a series of keys; means operated by the keys to shift each stud endwise in its slots; means controlled by the keys to rotate the drum through a distance equal to the distance between any two slots every time a key is operated; a series of swinging latches equal in number to the studs in one slot of the "record-drum," and normally resting on the surface of the drum in the paths of such studs as have been moved endwise, so as to be swung out by the said studs when moved over them; a constantly-revolving drum, with studs fixed on its periphery; a series of swinging bars placed over said revolving drum, each bar being operatively connected with one of the aforesaid latches; means whereby, when a latchet is swung out, its corresponding bar is raised when a stud on the constantly-revolving drum passes beneath the said bar; a series of shafts, capable of being rocked by the raising of the bars; and a series of punches operated by the rock-shaft to make a record in a paper strip; substantially as specified.

12. In a type-setting, type-writing or analogous machine the combination with a constantly-revolving drum having fixed studs on its periphery, and a series of bars placed over said drum, of a series of pivoted arms the free ends of which rest on the surface of the said drum in the paths of the studs and beneath the bars, each arm having an adjustable distance-piece, and means, operated by the revolving drum, to place the distance-pieces in and out of position between the bars and the arms substantially as and for the purpose specified.

13. In a type-setting, type-writing or analogous machine the combination with a constantly-revolving drum having fixed studs on its periphery, and a series of bars placed over said drum of a series of pivoted arms, the free ends of which rest on the surface of the said drum in the paths of the studs and beneath the bars, each arm having an adjustable distance-piece, and means, operated by the bars to place the distance-pieces in and out of position between the bars and the arms substantially as and for the purpose specified.

14. In a type-setting, type-writing, or analogous machine, and in combination; a constantly-revolving drum, having fixed studs on its periphery; a series of pivoted arms, the free ends of which rest on the surface of said drum in the path of the studs, each arm being raised when a stud passes under it; an

- adjustable distance-piece on the free end of each arm; a series of swinging bars; a keyboard having a series of keys; means operated by the keys, so that each key when struck 5 places two bars in position over the free end of said arms; a mechanism to shift the distance-pieces in and out of contact with the bars, so that the studs when passing under the arms are respectively operative and inoperative to raise the bars; means operated by a stud on the revolving drum to actuate the distance-pieces-shifting mechanism; and means operated by the bars to actuate the said mechanism when two keys of the keyboard are simultaneously struck; substantially as specified. 10 15
15. In a type-setting, type-writing or analogous machine and in combination; a constantly-revolving drum, having fixed studs 20 on its periphery; a series of pivoted arms, the free ends of which rest on the surface of said drum in the paths of the studs, each arm being raised when a stud passes under it; an adjustable distance-piece on the free end of each arm; a series of swinging bars, corresponding to said arms; a keyboard, having a series of keys; means operated by each key to place two of the bars in position over the free ends of the corresponding arms; mechanism to shift the distance-pieces in and out of contact with the bars, so that the studs when passing under the arms are respectively operative and inoperative to raise the bars; independent means, each operated by a stud on the revolving drum to operate the distance-pieces-shifting mechanism of each section; independent means each 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
- and reverse the normal order in which the bars are lifted, operated by special studs, a special pivoted arm having a fixed distance-piece, and a special "reversal-bar," said bar being placed in operative position when a special reversal key or pedal of the keyboard is struck simultaneously with two other keys; substantially as specified. 7c 75
17. In a type-setting, type-writing or analogous machine, and in combination; a constantly-revolving drum having fixed studs on its periphery; a series of pivoted arms, the free ends of which rest on the surface of said drum in the paths of the studs, each arm being raised when a stud passes under it; an adjustable distance-piece on the free end of each arm; a series of swinging bars corresponding to said arms divided into two sections; a keyboard divided into two sections, each section having a series of keys corresponding to each section of bars; means operated by each key of each section to place two of the bars in its corresponding section over the free ends of their corresponding arms; mechanism to shift the distance-pieces in and out of contact with the bars, so that the studs when passing under the arms are respectively operative and inoperative to raise the bars; independent means, each operated by a stud on the revolving drum to operate the distance-pieces-shifting mechanism of each section; independent means each operated by the bars of one section to operate the distance-pieces-shifting mechanism when two keys in the corresponding section of the keyboard are struck simultaneously; substantially as described. 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
18. In a type-setting, type-writing or analogous machine and in combination; a constantly-revolving drum having fixed studs on its periphery; a series of pivoted arms, the free ends of which rest on the surface of said drum in the paths of the studs, each arm being raised when a stud passes under it; an adjustable distance-piece on the free end of each arm; a series of swinging bars corresponding to said arms divided into two sections, a keyboard divided into two sections, each section having a series of keys, corresponding to each section of the bars; means operated by each key of each section to place two of the bars in its corresponding section over the free ends of their corresponding arms; mechanism to shift the distance-pieces in and out of contact with the bars, so that the studs when passing under the arms are respectively operative and inoperative to raise the bars; independent means, each operated by a stud on the revolving drum to operate the distance-pieces-shifting mechanism of each section; and means to operate the said mechanism of both sections and reverse the normal order in which the bars are lifted, operated by special studs and special arms and a special "reversal-bar" when a special "reversal key or pedal" of the keyboard is struck simultaneously with two keys, one in each 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

section of the keyboard; substantially as specified.

19. In a machine such as described the combination with a keyboard having a series of 5 keys arranged in parallel rows, all the keys of each row controlling a common mechanism to give a record of a single character, of means, substantially as specified, operated by the common mechanisms and controlled by the keys, which when a key in one row is struck simultaneously with a key of another row automatically determines the order in which the characters are recorded.

20. In a machine such as described having 15 an intermittently-moving "record-drum" with a series of longitudinal slots on its periphery, a series of studs in each slot, a series of latches or distance-pieces resting on the surface of the drum in the paths of the studs, 20 and a constantly-revolving "assembling-drum," the combination with the said latches of means operated by the "record-drum" to move the latches forward with each movement of the said drum, and means, operated 25 by the "assembling-drum" for moving back the said latches so as to engage with the studs of the "record-drum" during one complete revolution and one revolution only, of the "assembling-drum" substantially as 30 specified.

21. In a machine such as described, and in combination; a record-drum, carried on a rotatable shaft and having a series of longitudinal slots on its periphery; a series of studs 35 in each slot, means to intermittently rotate the drum through a distance equal to that between adjacent slots; a spindle carrying a series of latches or distance-pieces, equal in number to the studs in one slot and normally 40 resting on the surface of the drum, and in the paths of the studs, said spindle being carried at one end on an arm rotatable on the drum-shaft and at the other end on an arm fixed on a sleeve rotatable on the same; a collar 45 capable of endwise movement on the sleeve and having a catch adapted to be held by a spring against the alternating teeth of a pair of ratchet-wheels, fixed on the record-drum shaft; a vibrating lever adapted to shift 50 the catch from one ratchet-wheel to the other; a cam-wheel operative on the lever; a ratchet-wheel fixed to the cam-wheel and having its teeth engaged by a spring-pressed pawl carried on a vibrating arm operatively connected 55 with a rocking sleeve; a rocking arm; a pin adapted to lock the arm to the sleeve; said pin being carried by a forked arm, capable of reciprocation through a bell-crank lever, having a cam-surface engaged with a pin on 60 the aforesaid ratchet-spindle; a second rocking arm adapted to be locked to the first rocking arm by a pin supported by a second forked arm operatively connected to the first, said pin having a cross-head; a spring-controlled 65 catch adapted to engage said cross-head; and a constantly-revolving drum having studs

425^a and 425 arranged to rock the two rocking arms, substantially as specified.

22. In a machine of the kind described having an intermittently-moving "record-drum" 70 with a series of longitudinal slots in its periphery a series of studs in each slot; a series of latches or distance-pieces resting on the surface of the drum in the paths of the studs, means to place the latches over the 75 studs; and a series of curved arms resting on the latches, each arm having a pin engaged with a swinging bar; shaping the said arms so that when the latches are over the studs the curved edge of each arm forms an arc of 80 a circle of which the axis of the "record-drum" is the center substantially as and for the purpose specified.

23. In a machine such as described and in combination; an intermittently-rotating 85 drum, a series of longitudinal slots in said drum; a fixed casing surrounding the drum; a longitudinal slot in the casing; a series of slots running circumferentially from one edge of the longitudinal slot to the other edge; a 90 second series of slots alternating with the first, each slot starting from one edge of the longitudinal slot, and gradually merging into its adjacent slot; a series of studs in each of the slots of the drum, the studs being normally engaged in the first series of circumferential slots of the casing but capable of sidewise movement when in the longitudinal slot, and means, controlled by the keys of the keyboard to shift the studs so as to engage the second series of circumferential slots, substantially as described. 95

24. In a machine such as described the combination with a plurality of studs, movably carried in a slot in an intermittently-moving 105 drum of a plurality of pivoted arms, each arm having a forked end, normally held over one of the studs; a bellows operatively connected to each arm to cause its fork to engage the stud; a bar 264 having pins adapted to 110 engage the arms when engaged with their studs; a constantly-revolving cam 267 and lever 283 to reciprocate the bar; a spring-controlled bar 274 having pins which engage the arms and an offset 280; a catch 279, curved 115 arm 282, rocking spindle 283, curved arm 285 and cam 286, substantially as specified.

25. In a machine such as described the combination with the "record-drum" mounted on a rotatable shaft, of a ratchet-wheel fixed 120 on said shaft; an arm rotatably mounted on the shaft, carrying a spring-pressed pawl engaged with said ratchet-wheel; a link connecting said arm with the head of a bar 240, held in guides and capable of reciprocation in 125 two directions; a tooth on said head; means, actuated every time a key on the keyboard is struck to advance the bar and engage the said pin in a recess in a vertical bar 235, constantly reciprocated by a pivoted arm and 130 cam-groove 230, substantially as specified.

26. In a machine of the kind described the

combination with a series of pivoted arms, the free ends of which rest on the surface of a constantly-revolving drum, of adjustable members or distance-pieces, one pivoted on

5 the free end of each arm; a slot in each distance-piece; a common spindle resting in these slots; bars connecting this spindle with a second spindle hanging on swinging arms and held against the cam-surface of a disk 10 392 by a spring; a ratchet-wheel fixed to said cam-disk; a swinging arm carrying a spring-pressed pawl engaged with the ratchet-teeth; an arm fixed on a rocking shaft engaged with said swinging arm, and means, actuated by 15 the revolving drum to rock the shaft vibrate the swinging arm and rotate the cam-disk substantially as specified.

27. In a machine of the kind described and in combination; a series of pivoted arms the free ends of which rest on the surface of a constantly-revolving drum, having fixed studs on its periphery; movable distance-pieces on the free ends; a cam 392 operatively connected to said distance-pieces; a rocking 20 sleeve 397, having a depending arm operatively connected with the cam, and arms 177 carrying a bar 178; two bell-crank levers having a bar 179 fixed to their arms 180 and a spindle 184 to their arms 182; a bar 185 carried on arms 186 pivoted on said spindle, said arms resting on a bar 187 and having cam-lugs 188; a series of "permutation-bars" 25 placed over the free ends of the pivoted arms, each bar having a nose 176 and a catch 175, the nose 176 adapted to engage the bar 179, when its "permutation-bar" is raised, and rock the bell-crank arms 180, 182, causing the bar 185 to engage the catches 175 of the other "permutation-bars," and cut them out, 30 their noses 176 then rocking the sleeve 397; a catch 183 adapted to engage a bar 189 when the bell-crank arms are rocked, and means operated by the revolving drum to lower the bar 189 and release the catch, substantially as 35 specified.

28. In a machine of the kind described and in combination, a multiported valve having a plurality of disks, a series of holes in each disk corresponding in number but so arranged 40 that when in normal position no free passage is formed by the holes through all the disks, and a recess in the periphery of each disk; a rocking shaft corresponding to each disk, having an arm engaging in said recess, and means to rock the shafts and shift the disks so as to form one free passage through all the disks substantially as specified.

29. In a machine of the kind described and in combination a multiported valve comprising a plurality of rotatable disks, a recess in the periphery of each disk; a rocking shaft corresponding to each disk having an arm engaging in its recess; a second recess 45 in the periphery of certain of the disks, catches adapted to engage in said second recesses when their disks are shifted, and

means operated by the rocking arm of any one of the other disks to release said catches and allow their disks to return to normal 70 substantially as specified.

30. In a type-setting, type-writing or analogous machine the combination with a series of mechanical marks, placed in operative position by the keys of a keyboard, of a constantly-revolving drum having a series of fixed studs on its periphery, and means operatively connecting the studs and the mechanical marks to cause the studs to actuate the marks as the drum revolves; said studs 75 being so arranged as to successively operate each mark during one revolution of the drum substantially as specified.

31. In a type-setting, type-writing or analogous machine the combination with a plurality of mechanical marks corresponding to characters, a constantly-revolving drum having a plurality of fixed studs on its periphery corresponding to each mark, and means operatively connecting the studs and the mechanical marks to cause the studs to successively actuate each mark during each revolution of the drum; of means operated by the drum whereby only one stud is operative on each mark during each revolution of 95 the drum substantially as specified.

32. In a type-setting, type-writing or analogous machine the combination with a plurality of mechanical marks corresponding to characters, a constantly-revolving drum having a plurality of fixed studs on its periphery corresponding to each mark, and means operatively connecting the studs and the mechanical marks to cause the studs to successively actuate each mark during each revolution of the drum; of means operated by the marks whereby only one stud is operative on each mark during each revolution of 105 the drum substantially as specified.

33. In a type-setting, type-writing or analogous machine the combination with a plurality of mechanical marks corresponding to characters, a constantly-revolving drum having a plurality of fixed studs on its periphery corresponding to each mark, and means operatively connecting the studs and the mechanical marks to cause the studs to successively actuate each mark during each revolution of the drum; and means operated by the drum whereby only one stud is operative on 110 each mark during each revolution of the drum; of means, controlled by a key or pedal of the keyboard and operated by studs on the drum, to select the stud which actuates each mark during one revolution of the drum substantially as specified.

34. In a type-setting, type-writing or analogous machine, and in combination, a keyboard having two sections, each section containing a series of keys; two series of mechanical 130 marks corresponding to the keys of these sections, means operated by the keys of each section to place the corresponding marks in operative position; a constantly-revolving drum

- having a plurality of fixed studs on its periphery arranged in two series, each corresponding to a series of marks; means operatively connecting the studs and the marks to cause the studs to successively actuate the marks first of one section and then of the other during each revolution of the drum; and means, controlled by a special key or pedal of the keyboard and also by a mechanical 5
mark in each section and operated by special studs on the drum, to reverse the order in which the studs actuate the two sections of marks substantially as specified.
35. In a type-setting, type-writing or analogous machine, a keyboard divided into two 10 sections; one section having a series of keys, each key apportioned to two characters,

means controlled by the keys whereby each key when struck gives a record corresponding to its characters in a fixed order, a second section having a similar series of keys and means controlled by the keys whereby when a key is struck, a record is given similar in characters to that given by a key of the first section but in a reverse order substantially as specified. 20 25

In testimony whereof I have signed my name to this specification in the presence of two subscribing witnesses,

PERCY BERESFORD WRIGHT KERSHAW.
